SEVERING MECHANISMS

Lloyd G. Miller, Beverly, and Robert W. Bradley, Marblehead, Mass., assignors to United Shoe Machinery Corporation, Flemington, N.J., a corporation of New Jersey

Filed Sept. 15, 1959, Ser. No. 840,148

53 Claims. (Cl. 112—46)

The present invention relates to improvements in Goodyear inseam sewing machines of the type for attaching welts to lasted shoe uppers and sole members, such as disclosed in United States Letters Patent No. 2,900,933, granted August 25, 1959, upon application of James P. Carter.

In the inseam sewing machine of the prior patent a welt is severed automatically in advance of the sewing point through the use of a novel feeler for engaging the end of the welt first attached to the shoe at a point where it is firmly backed by the bulging last supported portion of the shoe upper as that end of the welt is approaching the point of operation of the stitch-forming devices a second time. The feeler is held away from the shoe during the major portion of each operation on the shoe to prevent interfering with the positioning movements imparted to the shoe by the operator. To insure proper operation of the feeler it is moved toward the shoe just before the end of the welt first attached to the shoe approaches the stitch-forming devices, so that the shoe may be directed by the guiding devices in the machine without obstruction from the feeler, except during a critical period near the end of the inseam.

In the machine of the prior patent the feeler is moved toward operating position in the machine by a knee-actuated lever mounted above the base of the machine. The knee lever is actuated as the end of the welt first attached to the shoe approaches the operating point and the lever is then held by pressure of the operator's leg against a knee pad on the lever while the inseam is nearing completion. At the same time the foot on the same leg of the operator is depressing a treadle at the base of the machine for otherwise controlling the sewing operation, so that as the operation is completed the operator raises his foot and thereby tends to produce undesirable skin abrasion by movement of his leg along the knee pad while holding the feeler in actuated position with relation to the shoe. To avoid undesirable skin abrasion a machine disclosed in United States Letters Patent No. 2,885,980, granted May 12, 1959, upon application of James P. Carter, provides a latch for holding the knee lever in actuated position without the necessity for the operator to give any further attention to the matter, a solenoid being provided to release the latch when the machine is coming to rest at the end of the seam.

It is an object of the present invention to improve the operation of a Goodyear welt shoe inseam sewing machine having a feeler actuated welt-severing knife of the type disclosed in the prior patents above identified, both in construction and in manner of operation by providing an electrical system whereby the constructional features of the machine are simplified and the functions of the machine previously performed by constructional features are accomplished by an arrangement of components in the electrical system. Further objects of the invention are to improve the operation and the versatility of the prior machine in its capability of accommodating itself to different types of work without complicated mechanical changes in the arrangement of the constructional parts of the machine and with a relatively simple, quickly effected expedient not requiring expert skill to accomplish. Another object is to improve the operation of the machine, especially in connection with the electrical sys-

2

tem in such manner as to enable the machine to operate effectively with less consumption of power and with greater reliability than heretofore. Still further objects relate to improvements in ease of construction and assembly, as well as in simplicity of adjustment and servicing during use of the machine.

Certain features of the invention consistent with the objects, above noted, reside in a machine for manufacturing shoes with a welt attached throughout their marginal portions including their heel seats, in which the usual stitch-forming, feeding, and guiding devices for the shoe parts are employed, and also in which a solenoid actuated welt-severing knife is mounted for movement toward and from the welt as it passes through guiding devices of the machine, the knife-actuating solenoid being incorporated in a circuit, including an energizing switch closed by a feeler engaging the leading end of the welt already attached to the shoe as that end approaches the stitch-forming devices a second time, and a shiftable carriage for the feeler is mounted for movement toward and from the point of operation of the stitch-forming devices, which machine is also equipped with a feeler positioning solenoid connected to the shiftable carriage, and safety control circuit means displaceable by the operator is provided for energizing the feeler positioning solenoid. Through the use of a separate solenoid for moving the feeler toward the point of operation of the stitch-forming devices less effort is required on the part of the operator in this respect and, accordingly, there is less opportunity for skin injury than when a knee lever acting mechanically is employed to move the feeler toward the work. In this feature the present invention constitutes an improvement over that disclosed in a prior application for United States Letters Patent, Serial No. 788,555, filed January 23, 1959 (now Patent No. 3,002,474, granted October 3, 1961), upon application of Lloyd G. Miller, one of the joint inventors in the present application.

In the machine of the prior application above referred to, an improved feeler and solenoid energizing switch of great sensitivity and reliability in operation are provided. In order to retain the sensitivity and reliability to best advantage, it has been found necessary to employ a relay having contacts for connecting the knife-actuating solenoid to a source of electrical power, of which the most conveniently accessible under present day practices is of the alternating current type. With the use of the improved feeler, as disclosed in the prior application, it has been found possible to locate the leading end on the welt as it approaches the sewing point a second time with such uniform accuracy in operating upon a sewed heel seat shoe, that a joint may be formed between the leading and trailing ends of the welt, defying detection except by probing with a sharp instrument. The uniformity with which accurate joint formation is preserved, according to another feature of the invention is retained while utilizing an alternating current supply source for the knife actuating solenoid and a relay through which the solenoid current is passed by connecting energizing contacts of a feeler actuated switch with a source of direct current, such as may be obtained through the use of an alternating current rectifier and a condenser subject to charge by the rectifier and for discharge through the coil of the relay, in order to avoid an unpredictable possibility of time lag as a result of closing the energizing contacts during a time of zero voltage in an alternating current cycle. If an alternating current source is connected by the relay energizing contacts at a time of zero voltage, a quarter of the alternating current cycle is required before full voltage is applied to the relay coil. This quarter cycle lag is sufficient in time duration to cause an erratic departure in the location of the severance line on the welt

as compared with closing the contacts at a peak voltage point in the alternating current cycle. Accordingly, such departure prevents uniformity of joint formation between the leading and trailing ends of the welt to an extent beyond the range of tolerance for acceptable work.

In another aspect of the invention, the electrical system employed is susceptible for convenient control through a single selector capable of effecting all expedients needed to place the machine in condition for operation, alternatively on sewing sewed heel seat shoes or on shoes having welts sewn about the foreparts only.

Other features of the invention relate to improvements in welt advancing mechanisms, improved frame constructions for facilitating adjusting and servicing the machine, novel work feeding mechanisms constructed particularly for effective lubrication, improvements in the stitch-forming and work-feeding devices for insuring proper formation of the first stitch of a new seam without excessive extension of the leading thread end, a novel form of thread break safety device to prevent the welt severing knife from being actuated at any time except at the end of a seam and improvements in driving and stopping mechanisms consistent with the welt severing control system and the thread-break safety device. These and other features of the invention as hereinafter described and claimed will readily be understood from the following detailed specification, taken in connection with the accompanying drawings, in which:

FIG. 1 is a perspective view looking from the right front of a machine embodying the features of the present invention;

FIG. 2 is a perspective detail view with parts broken away and shown in section and on an enlarged scale, illustrating the construction surrounding the point of operation of the stitch-forming devices in the machine of FIG. 1;

FIG. 3 is a reduced scale fragmentary view in front elevation of some of the stitch-forming, feeding and guiding devices surrounding the point of operation of the machine;

FIG. 4 is a detail view in front elevation of mounting and actuating mechanisms for a welt end feeler and guard in the machine of FIG. 1, the parts being shown with the feeler and guard in inoperative positions, retracted from their operating point on a shoe;

FIG. 5 is a detail plan view of the feeler and guard mounting and actuating mechanism shown in FIG. 4;

FIG. 6 is a sectional detail view of a mounting and base plate for the feeler mechanism taken along line VI—VI of FIG. 4;

FIG. 7 is a sectional detail view of the feeler and guard mounting, taken along the line VII—VII of FIG. 4;

FIG. 8 is a perspective detail view looking from the rear left of the feeler and guard, together with the base plate on which they are mounted, indicating the position of the parts while the feeler is retracted from operative position;

FIG. 9 is a detail view in left side elevation showing a unitary assemblage of the feeler mounting, a welt-severing knife mechanism, and a welt end advancing mechanism employed in the machine;

FIG. 10 is a detail view in front elevation and partly in section of the welt-severing knife and its actuating mechanism, together with a bracket for mounting the mechanism on the machine frame;

FIG. 11 is a sectional detail view taken along the line XI—XI of FIG. 10;

FIG. 12 is a plan view of a portion of the bracket on which the welt-severing mechanism is mounted, as seen from the line XII—XII of FIG. 10;

FIG. 13 is a sectional detail front view of the welt-severing knife actuating mechanism and its enclosing housing;

FIG. 14 is a sectional detail view of a manually ac-

tuated spring-pressed plunger for locking the welt-severing knife in welt cutting position, the parts being shown with the plunger engaging the knife actuating mechanism to hold it immovably;

5 FIG. 15 is a sectional detail view of the parts shown in FIG. 14 with the plunger in a position disengaged from the knife actuating mechanism;

10 FIG. 16 is a sectional detail view of the welt severing knife actuating mechanism with its mounting bracket and enclosing housing;

15 FIG. 17 is a perspective detail view, looking from the right front, of a welt-severing knife mounting bracket and a guideway cover plate arranged in separated relation therefrom;

20 FIG. 18 is a similar perspective view of mechanisms for actuating the knife, the feeler and the welt advancing mechanism with their mounting bracket laid on a supporting shelf while remaining electrically connected in circuit with other devices in the machine;

25 FIG. 19 is a detail plan view of a portion of welt-guiding and directing devices in the machine;

FIG. 20 is a detail view in right side elevation of the welt guiding and directing devices;

25 FIG. 21 is a detail view in front elevation of the welt-guiding and directing devices shown in operating relationship with the welt-severing knife;

30 FIG. 22 is a plan view of a shoe, illustrating the form at the leading end of the welt first attached to the shoe after being severed by the knife from the previously sewn shoe;

35 FIG. 23 is a detail view in front elevation of a portion of the welt-advancing mechanism;

FIG. 24 is a sectional detail view of the welt-advancing mechanism taken along the line XXIV—XXIV of FIG. 23;

35 FIG. 25 is a further sectional detail view of the welt-advancing mechanism looking in the direction of the arrow XXV in FIG. 23;

40 FIG. 26 is a fragmentary sectional detail view of a welt advancing wheel and a welt pressure roll employed in the welt-advancing mechanism, looking in the direction of the arrow XXVI in FIG. 23, the parts being shown while gripping a welt and in positions assumed during the advance of the welt;

45 FIG. 27 is a similar view of the same parts, illustrating their positions assumed during sewing operations with the welt passing freely between the advancing wheel and the pressure roll;

50 FIG. 28 is a fragmentary view partly in section, looking from the right side of the machine and showing portions of the mechanism for actuating the welt-advancing wheel, together with portions of a reversing and stopping mechanism for bringing the machine to rest;

55 FIG. 29 is a fragmentary sectional view of a portion of the mechanism shown in FIG. 28, illustrating the positions of parts during stopping;

FIG. 30 is a sectional detail view of a portion of the welt advancing mechanism taken along the line XXX—XXX of FIG. 28;

60 FIG. 31 is a perspective detail view of a counting device for the stopping mechanism illustrated with the machine in stopped position;

FIG. 32 is a further perspective detail view of the counting mechanism illustrated just before the machine is stopped;

FIG. 33 is a perspective detail view looking from the left rear of a locking latch for a thread break safety lever;

FIG. 34 is a view in rear elevation of a portion of a shoe being operated upon, showing the insertion of the first stitch in a seam by the machine;

65 FIG. 35 is a perspective detail view, partly in section taken along the line XXXV—XXXV of FIG. 34, the parts being otherwise shown in the same relationship as those in FIG. 34;

FIG. 36 is a view in elevation of the same parts as

those shown in FIG. 34, illustrating the position of the sewing needle after being withdrawn from the shoe with a loop of thread;

FIG. 37 is a sectional perspective view taken along the line XXXVII—XXXVII of FIG. 36 with the parts in positions corresponding to those of FIG. 36, the awl being shown after engaging the welt for the first time;

FIG. 38 is a view similar to that of FIG. 36, illustrating the formation of the second stitch in a seam;

FIG. 39 is a perspective detail view taken in section along the line XXXIX—XXXIX of FIG. 38;

FIG. 40 is a developed view of a groove in a feed cam employed in the machine;

FIG. 41 is a fragmentary view in right side elevation and partly in section, showing the needle actuating and feeding mechanisms;

FIG. 42 is a similar view showing the awl actuating and feeding mechanisms;

FIG. 43 is a plan detail view, partly in section, of a mounting yoke and lever in the needle feeding mechanism;

FIG. 44 is a detail sectional plan view of the awl feeding mechanism;

FIG. 45 is a fragmentary sectional detail view taken along the line XLV—XLV of FIG. 44, illustrating an adjustment of the mechanism, in which the longest possible feeding movement is imparted to the awl;

FIG. 46 is a similar fragmentary view, illustrating an arrangement of the awl feeding mechanism for lubricating it when adjusted for a reduced feeding movement;

FIG. 47 is a sectional detail view of the mounting yoke, looking from the right and including cam levers for the needle and awl feeding mechanisms, illustrating an arrangement of fulcrum pins for maximum feeding movement of both levers;

FIG. 48 is a detail sectional view taken along the line XLVIII—XLVIII of FIG. 47 showing a portion of a fulcrum pin in the awl feed lever supporting yoke in a position for producing maximum awl feeding movement;

FIG. 49 is a similar sectional view of the awl fulcrum lever pin in a position for producing a reduced awl feeding movement;

FIG. 50 is a sectional plan view of a portion of the needle feed lever, taken along the line L—L of FIG. 47, with the needle fulcrum lever pin in a position for producing a maximum needle feeding movement;

FIG. 51 is a similar sectional plan view of the same parts but with the needle lever fulcrum pin adjusted to a position for a reduced needle feeding movement;

FIG. 52 is a perspective view looking from the right front of the feed lever supporting yoke and including, in separated relationship, portions of a mounting mechanism for a welt guide in the machine;

FIG. 53 is a detail plan view, partly broken away and enlarged in scale, of a preliminary welt guide and welt antiretraction device employed in the machine;

FIG. 54 is a sectional detail view in left side elevation of the guide and antiretraction device;

FIG. 55 is a detail view in front elevation of the guide and antiretraction device;

FIG. 56 is a detail view in right side elevation and partly in section of the knee controlled lever displaceable by the operator of the machine for preparing the machine for automatically severing the welt in a sewed heel seat shoe or, alternatively, for causing the welt severing knife to be prepared for actuation while sewing a shoe having a welt sewn from breast line to breast line only.

FIG. 57 is a detail view in left side elevation and on a reduced scale of a pair of treadle actuated microswitches for controlling the operation of the welt-severing knife;

FIG. 58 is a detail view in right side elevation, partly broken away and shown in section, of portions of the machine including a limited slack thread pull-off device to insure the formation of a tight first stitch inserted by the machine and a thread break safety lever and switch

therefor, taken with the parts in positions assumed after a thread break;

FIG. 59 is a perspective detail view of a thread break safety lever shown in FIG. 58;

FIG. 60 is a plan view of the upper portion of the machine, including a slack thread pull-off lever, the thread break safety lever and a switch controlled thereby;

FIG. 61 is a view in right side elevation of the parts shown in FIG. 60 taken in positions assumed while the machine is stopped under normal conditions without thread breakage;

FIG. 62 is a detail plan view, illustrating portions of a shoe and certain of the stitch-forming devices, such as employed in a prior machine just before the machine is started in operation at the beginning of an inseam, the take-up and tension wheel being illustrated for convenience in laterally offset relationship to the other parts;

FIG. 63 is a similar view of some of the same parts taken after 130° of rotation of the sewing shaft;

FIG. 64 is a similar view taken after insertion of three stitches and continued movement of the sewing shaft through 130° of rotation during formation of the fourth stitch in a seam;

FIG. 65 is a view similar to that of FIG. 62 but showing the present machine with a limited slack thread measuring device, illustrating its operation just before the machine is started at the beginning of an inseam;

FIG. 66 is a similar detail view, illustrating the positions of certain of the parts shown in FIG. 65 after rotation of the sewing shaft through 130°;

FIG. 67 is a similar detail view taken after the insertion of three stitches and continued rotation of the sewing shaft through 130°, the first stitch of a new seam being illustrated in substantially tightened relationship in the work; and

FIG. 68 is a wiring diagram for the machine of the present invention, showing the electrical control system for the machine.

The machine illustrated in the drawings is a Goodyear 40 welt shoe inseam sewing machine, such as that disclosed in the patents and application above identified. The machine of the patents and application is provided with welt-severing, attaching devices, and feeding and guiding devices capable of operating entirely around the marginal portions 45 of a last-supported Goodyear welt shoe upper and a sole member. A welt-severing knife or other tool for performing an auxiliary operation is mounted for movement toward and from the welt as it passes through its guiding device, automatic mechanism being provided for actuating 50 the knife or tool, including an electromagnetic solenoid, an armature connected to the knife, and a feeler of extremely light weight and sensitivity mounted for engagement by the leading end of the welt already attached to the shoe, as that end approaches the stitch-forming devices a second 55 time. The prior machine is intended for operation upon a shoe which has a welt sewn thereto throughout the length of the bottom marginal portions, including the heel seat of the shoe or, alternatively for sewing or otherwise attaching a welt about the forepart only of the shoe.

60 As illustrated in FIGS. 2, 22, and 35 to 39, inclusive, of the drawings, the parts of a shoe including an insole 2, an upper 4, mounted on a last 6 and a welt 8, are operated upon by the attaching devices in the form of stitch-forming and feeding devices, which insert an inseam 10 and the 65 leading end, indicated at 12, of the welt first attached to the shoe is engaged by the feeler, indicated at 14, mounted for movement toward and from a position of engagement with the welt end 12 during the feeding movement of the shoe as the welt end approaches the point of sewing operations. As the welt end 12 approaches the stitch-forming devices a second time, the welt-severing knife, indicated at 16 (FIG. 2) is projected against the welt along a path inclined to form an obtuse angle ridge on the welt running from a suitable supply at a position sufficiently in advance 75 of the point of operation of the stitch-forming devices so

that danger of contact with the parts of the shoe other than the welt will be avoided as the sewing operation continues, the machine operating thereafter until one or more stitches are inserted overlapping the ends of the welt which are brought into close fitting abutting relation with each other. The angle formed by the knife on the trailing end of the welt always supplements the obtuse angle formed on its leading end, thus contributing to a close fitting bevel joint. The machine is then brought to rest by driving and stopping mechanisms under the control of the operator and other intermittently acting mechanisms are thrown into operation for advancing the end of the welt remaining in the machine across the sewing point in preparation for the start of an inseam on a new shoe. To start the machine the operator depresses a foot treadle 18 at the base of the machine (FIG. 1) and to stop it he releases the treadle, a spring 20 raising the treadle.

In the machine of the prior Carter Patent No. 2,900,933, the feeler is mounted upon a shiftable carriage for movement toward and from a shoe being operated upon and is held away from the shoe during the major portion of each operation. Toward the end of the seam inserted by the machine, the operator presses his leg against a knee pad on a displaceable lever which, in turn, is connected through a cable to the carriage to move the feeler mechanically toward the shoe. In so doing, he utilizes the leg which is also employed to depress the treadle, his other leg being required for his main support and balance. To hold the feeler in operating position after movement toward the shoe, it is necessary for the operator to apply a continued pressure of his leg against the knee pad until after the sewing operation is completed. Before the end of the seam it is necessary for the operator to release the control treadle, but in releasing it his leg already pressing against the knee pad is subject to undesirable skin abrasion or excessive clothing wear along the knee pad. Even though a latch is provided in the improved machine disclosed in Patent No. 2,885,980, there still is a necessity for moving the feeler carriage toward the shoe, possible difficulty with skin abrasion still being present by reason of the desire on the part of the operator to delay movement of the feeler toward the shoe until the last possible moment and then to press the knee pad with a sudden impact, almost instantaneously slightly before the release of the treadle 18.

In the machine hereinafter described, the problem of skin abrasion and ease of feeler movement toward the point of operation on a shoe is largely eliminated by the use of a feeler positioning solenoid connected to the shiftable carriage on which the feeler is mounted, all of the force required for moving the feeler and carriage quickly and accurately and for holding the feeler in operative position with relation to the shoe being supplied by the solenoid rather than through the operator's leg. To energize the feeler positioning solenoid, a light microswitch connected to a conveniently available source of electric power is utilized, so that the operator need supply only the force required to operate the microswitch in shifting the feeler and carriage toward a shoe being operated upon.

Referring to FIGS. 3 to 9, inclusive, the feeler 14, as more fully described in application Serial No. 788,555, is mounted for bodily movement upon a shiftable carriage comprising a side plate 22, a pair of bolts 24, and 26 passing through a guard 28 for the feeler and through an arcuate slot of a track 30 along which the carriage is confined to a curved path inclined toward the bulging upper of the shoe and is movable toward and from the operating point of the machine. During the major portion of each sewing operation on a shoe the feeler and guard are held in a position retracted from the shoe by a tension spring 32 stretched between a pin 34 and an angular link 36 (FIG. 8). The pin 34 is mounted in a base plate 38 forming a part of the track 30 and being secured to a box-like guideway within which is a sliding bar connected at its lower end to the knife 16. The link

36 has an opening in its lower end through which passes the bolt 24 of the feeler and guard carriage. Although the carriage moves the feeler toward the sewing point, the feeler is brought to rest at a position spaced from the sewing point exactly by the distance from the sewing point at which the knife severs the welt, so that an accurately matched joint is formed between the welt ends.

The solenoid for actuating the feeler and guard carriage is equipped with an armature disk 40 (see FIG. 6) 10 rotatably mounted through approximately 90° on the rearward side of the solenoid whenever it is energized. Projecting rearwardly from the disk 40 is a crank pin 42 mounted eccentrically on a central disk supporting shaft 44. Surrounding the end of the crank pin 42 is the upper 15 end of a connecting link 46 also pivotally connected to a pin 48 (FIG. 4) at its lower end on the feeler carriage side plate 22. The shaft 44 of the solenoid is rotatably mounted in a frame 50 within a hollow housing 52 (FIG. 6). The frame is secured to the housing by a pair of screws 54 (see also FIG. 4) and the housing 52 is made fast to the base plate 38 by a set of four screws, one of which is indicated at 56 in FIG. 6, passing through the base plate 38 into lugs at the rear edge of the housing 52.

To energize the feeler positioning solenoid in the illustrated machine, there is mounted at a position convenient for actuation by the leg of the operator a displaceable knee lever shown at 58 in FIG. 1 beneath a shelf 60 projecting forwardly from a supporting column 62 mounted on a base 64, as in the machines of the prior patents and application, the treadle 18 being pivotally mounted at its rearward end on the rear of the base.

As best shown in FIG. 56, the displaceable lever 58 is fulcrumed on a pin 66 secured in a downwardly extending lug of a mounting plate 68, the mounting plate being 35 made fast by screws 70 to the underside of the shelf 60. To limit the movement of the knee lever 58 a forked portion near its fulcrum embraces the lug on the mounting plate 68 and is provided with adjustable stop screw 72 arranged to engage the sides of the lug on the mounting 40 plate. To the lower end of the lever 58 is adjustably attached a knee pad 74, the weight of which is slightly overbalanced by a counterweight 76 clamped to a bar 78 extending rearwardly from a central portion of the lever 58. Projecting rearwardly from the lever is an arm 45 disposed beneath an actuating rod 80 for an operator actuated safety microswitch LS3 capable of being actuated to close a circuit to the feeler positioning solenoid, indicated at 82 (FIG. 6). The arrangement is such that an extremely light pressure on the knee pad 74 is sufficient to actuate the microswitch LS3 and to produce the desired results.

Instead of requiring the continued pressure of his leg against the knee pad 74, in order to hold the feeler 14 in operative position with relation to the shoe, the operator 55 of the present machine needs only to press the knee pad for an instant, sufficiently to actuate the microswitch LS3. The circuit controlled by the microswitch LS3 is designed to continue the current flow through the feeler positioning solenoid until after the welt is severed, as will be described.

The circuit for the feeler positioning solenoid 82 is energized from a source of alternating current comprising a supply line 84, running from a transformer shown in FIG. 68. The supply line is connectible or disconnectible 65 from the illustrated machine through the operation of a line switch 86, having a handle projecting from a control box 88 (FIG. 1) secured beneath the shelf 60 at the front of the machine. One side of the line is connected through certain other connecting switches to the safety 70 microswitch LS3. When the safety microswitch is closed it completes a circuit through a part of a three element selector switch and through a resistor R1 and a rectifier 90 to the feeler positioning solenoid 82, which is connected to the other side of the line. As soon as the feeler positioning solenoid is energized the feeler 14 is moved

into operative position with relation to the shoe where it is held as long as the feeler positioning solenoid is energized.

To hold the feeler and its shiftable carriage in operative position with relation to the shoe, in this feature of the present invention, the knee actuated safety microswitch LS3 also acts to close a circuit through a coil of a feeler carriage safety relay K1 and to prepare the circuit for severing the welt. When the coil of the relay K1 is energized, holding contacts K1A in the safety relay shunt the safety microswitch LS3. Closure of the contacts K1A insures a continuity of current flow through the safety relay K1 after the displaceable lever is released and until such time as the circuit otherwise is interrupted. Interruption of the safety relay circuit occurs after the welt has been severed, so that the parts are then restored to their original conditions. To insure a reliable non-vibrating action in the feeler positioning solenoid 82, the resistor R1 and the rectifier 90 cooperate with the inductance of the feeler positioning solenoid and a condenser 92 connected across the solenoid to provide a relatively smooth direct current flow through the feeler positioning solenoid.

As soon as the feeler 14 on its mounting carriage is moved into operative relationship with a shoe, the leading end 12 of the welt engages the feeler as the operation progresses and completes a circuit through a solenoid energizing switch 94 having a set of contacts in circuit with a current limiting resistor R3 and the coil of a knife-actuating relay K3. The knife actuating relay K3 has a set of contacts K3B connected in circuit with a Welt-Severing Solenoid 95, shown structurally in FIGS. 9, 10, 13, 16 and 17, closure of the contacts K3B completing the circuit to the solenoid. As soon as the circuit is completed through the solenoid 95, an armature 96 (FIG. 13) having a nonmagnetic lower end is pulled downwardly against a bar, indicated at 97 (FIGS. 10 and 17), at the lower end of which is connected the knife 16, the bar 97 being slidably in the box-like guideway, indicated at 98, which forms a foundation for the feeler supporting base plate 38 (see FIG. 17). The knife 16 is connected for lengthwise adjustment relative to the lower end of the bar 97, being disposed in a channel at one side of the bar and clamped in position within the channel by a screw 100 passing through a slot in the lower end of the bar and being threaded into the upper end of the knife 16. To retract the knife after being actuated, the bar 97 has a lengthwise slot within which is mounted a coil spring 102 (FIG. 10) pressed between a semicylindrical stud 104 on the box-like guideway at its lower end and on a connecting portion of the bar at the upper end of the slot to restrain the bar and knife in their uppermost inactive positions. When the welt-severing solenoid 95 is energized, the bar and knife are projected downwardly at an angle to the welt running through a preliminary enclosure 106 forming a cutting guide for the knife, the knife passing between the preliminary guide and a sewing welt guide 108 (see FIGS. 19, 20 and 21).

The cutting and sewing welt guides are both mounted at the forward end of a welt guide carrier bar 110 (FIG. 52), which is pressed yieldingly forwardly until the sewing welt guide engages the shoe and which is intermittently locked against rearward movement during certain portions of each sewing cycle in the machine, as disclosed in United States Letters Patent No. 2,647,478, granted August 4, 1953, upon application of F. C. Eastman. At the forward end of the bar 110 is an enlargement having a vertical groove 112 fitting a tongue 114 on a plate 116 (FIGS. 19 and 20), the plate being attached to the welt guide bar by a bolt 118 (FIG. 3) passing through an L-shaped slot 120 (FIG. 21) in the plate 116. Also attached to the plate 116 by a cap screw 122 is an angle bracket 123 for supporting the preliminary welt enclosure 106 (FIG. 20), a bolt 124 formed with a rectangular head passing through slots in rearwardly extending arms of the welt

enclosure and a U-shaped mounting block 125 resting on the upper surface of the angle bracket 123, within the U of which block rearwardly extending arms of the enclosure are confined.

5 Rearward ends of the sewing welt guide 108 are disposed within opposed channels of a mounting block 126 and a clamp bolt 128 passes through the welt guide and the block 126. The block 126 has a pin extending from its right side, which pin projects into a split clamp portion of a swivel block 130. The swivel block 130 has a shank fitting a similar split clamp portion on the plate 116, a screw 132 passing through the split clamp portion of the plate 116 to secure the pin on the swivel block 130 in suitable adjusted position on the welt guide carrier bar 110. This construction is otherwise similar to that disclosed in Patent No. 2,900,933, above referred to, and in an application for United States Letters Patent Serial No. 789,842, filed January 29, 1959, now Patent No. 2,972-969, granted February 28, 1961, in the name of Lloyd G. Miller.

20 It is essential in the use of any Goodyear welt inseam sewing machine to have the shoe being sewn held in firm engagement with the sewing welt guide 108 at all times in order to insure that the welt sewn is accurately directed against the shoe with stitches inserted within the welt groove, indicated at 134 in FIG. 19. For this purpose it is highly desirable that the positioning movements of the shoe, as presented to the machine by the operator be kept as free from other obstruction as possible. Accordingly, the feeler 14 and its guard 28 are withdrawn from operative position as soon as the welt-severing knife is actuated to sever the welt.

25 For withdrawing the feeler 14 and the guard 28 from operative position with relation to a shoe as soon as the welt-severing knife is actuated to sever the welt, there is connected in series with the circuit to the feeler carriage safety relay K1 a normally closed set of contacts K2A of a knife releasing relay K2 having a coil connected at one end to one side of the line 84 and at the other end to a set of normally open contacts K4A of a time delay relay K4. The time delay relay has a coil in series with a set of contacts K3B of the knife-actuating relay K3. When the knife-actuating relay closes the contacts K3B upon engagement of the feeler with the leading end of the welt 8 on a shoe, the time delay relay K4 is energized but the contacts K4A do not close the circuit to the knife releasing relay K2 until after a lapse of a predetermined time interval. This time interval is short but is necessary to insure maintaining the knife actuating relay K3 energized until after a full length cutting stroke of the welt-severing knife 14 has been completed. Without such time interval it is possible that the contacts in the feeler actuated switch 94 might become disengaged as the severing knife reaches a midposition of its cutting stroke, and, accordingly, the knife might be retracted before severing the welt. With the use of the time delay relay this difficulty is obviated and a full cutting stroke of the knife is always completed each time the feeler actuated switch 94 closes its circuit.

30 35 40 45 50 55 60 65 70 75 As soon as the time delay relay K4 closes the contacts K4A in the circuit to the knife releasing relay K2, a normally closed set of contacts K2B in the releasing relay are actuated to open the circuit to the welt-severing solenoid 95. At the same time that the welt-severing solenoid circuit is opened by the knife releasing contacts K2B, the normally closed contacts K2A open the circuit to the feeler carriage safety relay K1, whereupon the contacts K1A are separated and the circuit to the feeler positioning solenoid 82 is opened.

The feeler carriage safety relay K1 also has a set of contacts K1B connected in series with the feeler actuated switch 94, so arranged that before the displaceable lever 53 is actuated by the operator there will be no danger of operating the welt-severing knife by reason of accidental movement of the feeler, the feeler switch circuit being

held open by the contacts K1B. Thus, the time delay relay K4 causes the circuit to both the feeler relay K3 and the knife actuating relay K2 to be opened simultaneously and the circuit to the feeler actuated switch 94 to be opened after a predetermined time interval has elapsed. The circuit through the feeler actuated switch 94 is not closed until the knee lever 58 is again actuated by the operator at a time when the end of the welt first attached to a new shoe approaches the sewing point in the machine a second time.

In the machine of Patent No. 2,900,933 the welt-severing feeler controlled switch is of relatively high current carrying capacity and is actuated mechanically from the feeler, there being no separate relay between the solenoid energizing switch and the feeler switch. For this reason a relatively heavy, sturdy construction is required in the feeler of Patent No. 2,900,933. Although that feeler operates uniformly with acceptable accuracy in severing the welt to match the leading end already attached to a shoe, it is less sensitive and accurate in its operation than that employed in the present machine. With the use of the improved feeler and its positioning mechanism employed in the present machine, as disclosed in application Serial No. 788,555, and without further modification and provision of heavier contacts having adequate current carrying capacity for the requirements of the welt severing solenoid 95, direct connections with the solenoid for energizing it from the feeler switch circuit have been found impractical and to reduce the durability of the contacts in the feeler switch excessively. In the use of the knife actuating relay K3 to reduce the current carrying requirements in the feeler switch contacts, however, it is found that a new element of inaccuracy and lack of uniformity are introduced in matching the trailing end of the welt with the leading end already attached to a shoe.

In order to take advantage of the improved feeler of light weight sensitive construction disclosed in application Serial No. 788,555, according to the present invention, the knife-actuating relay K3 is connected for operation in an improved circuit for which power is provided for the solenoid 95 directly by the alternating current supply line 86 but in which the power supplied to the knife actuating relay K3 is of the direct current type. For providing direct current to the knife-actuating relay K3 a rectifier and a condenser are introduced into the circuit of the relay in such relation to each other that the condenser will be charged by the rectifier and will be discharged by the feeler actuated switch 94 through the coil of the knife-actuating relay K3 whenever the feeler is engaged by the end of a welt on a shoe. The use of direct current in this way is of particular benefit in providing uniform and accurate operation of the welt-severing knife actuating solenoid 95, but is of further benefit where an alternating current supply is employed with the use of transformers to insure high-speed operation of a welt severing solenoid designed for much heavier current flow than could be controlled conveniently by a mechanically connected feeler switch, as in application Serial No. 788,555, the sensitivity of the feeler and the speed of operation of the knife against the welt and the current consumption of the solenoid being important factors in effective high-speed severance of the welt during continued operation of the machine at regular sewing speeds.

Referring further to FIG. 68, the knife-actuating relay K3 has connected in series with its coil the current limiting resistor R3, which prevents building up of transient currents in the knife actuating relay coil circuit and consequent undesirable arcing in the feeler switch 94 during engagement of its contacts. Direct current is supplied to the coil of the knife-actuating relay K3 from a condenser 136, the negative plate of which is connected to one side of a transformer 138 and the positive plate of which is connected for charging by a rectifier 140. The rectifier 140 is further connected through a ballast resistor R2 with the other side of the transformer 138. Between the

condenser 136 and the rectifier 140 is a branch line 142 running in one direction through a thread break safety switch 4LS and safety relay contacts K1B, through contacts while in a position "SS" of a double throw element, indicated at 144, of the selector switch and a wire 146 running to the feeler switch 94, the contacts K1B being actuated by the relay K1. At the other side of the feeler switch 94 is a connecting wire 148 running to a junction 150 at one end of the resistor R3. To prevent irregular action of the relay K3 it is provided with holding contacts K3A which close when the relay is energized and connect the branch line 142 in another direction with the knife actuating relay. The arrangement is such that when the feeler switch 94 closes its contacts the condenser 136 is discharged through the coil of the relay K3. As soon as the feeler switch 94 opens its contacts the condenser 136 is recharged ready for another operation and the contacts K3A hold the relay circuit closed until the transformer 138 is deenergized, as will be described. With such circuit connections there is no possibility of an irregular elapse of the time between the closing of the contacts of the feeler switch 94 and the actuation of the relay K3 as a result of closing the contacts of the feeler switch during a zero point of an alternating current cycle in one instance or at a point of maximum voltage in another instance. Accordingly, the welt-severing solenoid 95 is energized in a predictable manner and the knife 16 is actuated always with an acceptably uniform time interval elapsing between instants of closing the contacts in the feeler switch and the completed severance of the welt. With the same elapsed time intervals between actuations of the feeler switch and of the knife, adjustments may be made in the machine to insure accurately matching the trailing welt ends with the leading welt ends already attached to the shoe, full advantage of the light-weight sensitive feeler construction thus employed being thereby preserved.

To enable convenient control of the machine for alternative operation on sewed heel seat shoes or on shoes having welt sewn about the foreparts only, all of the essential changes required for either one or the other type of operation is performed by the selector switch comprising its three elements mounted in the control box 88 and having a handle 152 projecting through the front cover at a readily accessible location, as shown in FIG. 1. As illustrated in FIG. 68, the selector handle 152 is actuated to a position marked "SS" where the machine is converted for operation upon sewed heel seat shoes. When shifted into the "BB" position the machine is converted for operation upon shoes having welt sewn about their foreparts only, no other adjustments being required in the electrical system to place the machine in condition for such types of operation. When the selector handle 152 is shifted to the "SS" position, a selector switch element 154 is moved to open circuit position, a selector element 156 is moved to closed circuit position and the switch element 144 is moved into engagement with the contact "SS" to complete the circuit between the contacts K1B and the feeler actuated switch 94. All of the selector switch elements 156, 154 and 144 are connected together for simultaneous movement by the selector handle 152.

When the selector handle 152 is moved to the "BB" position, the machine is converted for operation upon shoes having a welt sewn only from breast line to breast line, the seam not being inserted about the heel seat portion in the "BB" position. In moving to the "BB" position, the selector handle 152 moves the element 156 to disconnect the main line from the feeler positioning solenoid 84 and to render it inoperative, the feeler not being required for the breast to breast sewing operation. The selector switch element 144 is also moved to the position "BB" away from the position "SS," so that the feeler switch 94 also is disconnected from its circuit.

Instead of using the feeler switch 94 for breast-to-

breast work, the circuit of the knife-actuating relay K3 is controlled by an operator controlled switch 6LS (FIG. 57) which is held closed until the starting treadle 18 is depressed by the operator's foot. When the treadle 18 is depressed in starting the machine in operation, the operator controlled switch 6LS is opened, this switch being connected in series with the knife-actuating relay energizing circuit in place of the feeler switch 94. The purpose of the switch 6LS is to act in place of the feeler switch 94 to discharge the condenser through the coil of the knife-actuating relay K3 as the machine is being brought to rest to cause the welt-severing solenoid 94 to be energized before the machine is stopped. This operation of the switch 6LS is accomplished by a link 158 (FIG. 1) pivotally connected at its ends to the treadle 18 and to a lever 160 mounted for movement about a fulcrum 161 in the column 62 of the machine. The lever 160 is in turn pivotally connected by a push rod 162 to a forwardly extending arm of a lever 164 secured to a shaft 166 rotatable in a plate 168 (see FIG. 57) mounted just below the head of the machine at the rear of a switch box 170 (FIG. 1). Clamped to the shaft 166 within the switch box is an arm 171 (FIG. 57) operatively connected to a sliding button in the switch 6LS. As the sewing point progresses about a breast-to-breast sewed shoe the operator of the machine actuates the knee lever 58 in the usual manner, causing the coil of the safety relay K1 to be energized and the contacts K1A and K1B to be closed. Thereafter, the operator removes his foot from the control treadle 18 to bring the machine to rest and the switch 6LS is closed, completing the circuit to the knife-actuating relay K3 and causing the welt-severing solenoid to be energized.

While the machine is at rest and the selector switch is in the "BB" position, it is impossible to energize the safety relay K1 regardless of the position of the selector switch elements 154, 156 and 144. This is because the arm 171 is arranged to engage a sliding button in a normally closed switch LS2 while the machine is at rest and to hold open the contacts of that switch, which are connected between the selector switch element 154 and one side of the line 84. When the control treadle 18 is depressed in starting the machine in operation, the arm 171 is moved away from the button on the switch LS2, closing the circuit from the line 84 through the contact K2A to the knee actuated safety switch LS3, which remains open until the knee lever 58 is actuated.

To insure that the circuit through the safety relay K1 is held closed when sewing sewed heel seat shoes a shunt circuit is provided about the switch LS2, including the selector switch element 154 and a set of safety relay contacts K1C. As soon as the safety relay K1 is energized while sewing sewed-seat shoes the contacts K1C are closed, completing the shunt holding circuit, the selector switch element 154 being closed during sewed-seat sewing. With this arrangement it is possible for an operator in sewing sewed heel seat shoes to actuate the knee lever 58 and to release the foot treadle immediately thereafter without danger of causing improper operation of the welt-severing knife.

Not only does the treadle controlled switch LS2 prevent energization of the safety relay K1 while the machine is stopped, but it also disconnects the transformer 138 from the main supply line 84, so that there is no danger of shock or sparking in the contacts of any of the switches or controls in the feeler switch circuit or in the knife-actuating relay K3. After the relay K3 has been energized, an additional shunt holding circuit around the feeler contacts is completed through auxiliary contacts K3A to hold the relay K3 circuit energized until opened by deenergizing the safety relay K1 through opening of knife releasing relay contacts K2A.

The welt-severing knife 16 of the present machine, being actuated by the electrically energized solenoid 95, severs the welt at high speed and without special attention in

the way of adjustment or necessity for continually maintaining a highly sharpened cutting knife edge. To accomplish the best results while operating upon sewed heel-seat shoes employing relatively light flexible welt, the supplemental welt cutting guide enclosure 106 must be adjusted into close proximity with the path of the knife. To simplify adjustments, means is provided in the illustrated machine for moving the knife manually downwardly into a cutting position relatively to the cutting guide 106 and for locking the knife against retraction by the spring 102.

For moving the welt-severing knife and for locking it in welt-severing position with relation to the cutting guide 106 in the illustrated machine, as best shown in FIGS. 10, and 13 to 16, inclusive, the upper end of the knife actuating armature 96 has projecting from it a manually actuated bar 172, and the base plate 38 for the feeler carriage foundation has a guide sleeve 176 attached to it by screws 174 (see FIG. 10), passing through flanges of the guide sleeve, within which sleeve is slidably mounted a spring-pressed plunger 178 (FIGS. 14 and 15). The outer end of the guide sleeve has a diametrical cut to form a step cooperating with a step cut hub on a knurled head 180 pinned to the outer end of the plunger and arranged to be rotated from the position of FIG. 14 into the position of FIG. 15. When in the position of FIG. 14 the rearward end of the plunger is permitted to enter an opening 182 in the lower end of the armature 96. When the armature is shifted downwardly to its lowermost position, the welt severing knife 16 enters within the space between the preliminary welt cutting guide enclosure 106 and the sewing welt guide 108, so that the welt may be positioned accurately in contact with the knife. To shift the armature 96 into its lowermost position the bar 172 is pulled downwardly. During normal operation of the machine the plunger 178 is held retracted from the armature 96, as in FIG. 15, by engagement of the high part on the step cut of the knurled head 180 with the high part of the step cut on the guide sleeve 176. To retain the knurled head in position with the plunger retracted from the armature, the high part of the step cut on the knurled head is formed with a small tooth 183 engaging a similarly shaped recess on the high part of the step cut on the guide sleeve 176. To prevent upward retraction of the armature 96 from within the solenoid 95 the lower end of the armature has passing through it a pin 184 projecting rearwardly from the armature to a position where it will engage an undersurface of the solenoid core 94 as the armature is raised.

The box-like guideway 98 for the bar 97 forms a part of a conveniently dismountable supporting structure for the feeler, the welt advancing, and the severing knife actuating mechanisms. The box-like guideway is illustrated more particularly in FIG. 17 and comprises a downwardly extending portion of a bracket 185 which is mounted on the main head frame of the machine, indicated at 186 (see FIG. 28), the bracket being secured in place on a tongue portion of the main frame entering a groove 188 in the bracket by a pair of cap screws 190 (see also FIG. 28) passing through holes 191 in the bracket and into threaded engagement with the main frame. Upon removal of the screws 190 the bracket with the feeler, welt severing, and advancing mechanisms may be removed from the machine as a single cooperative unit so that they may be serviced and adjusted separately from the other mechanisms in the machine.

For mounting the solenoid 95 on the bracket 185, the bracket has two forwardly projecting arms into which are threaded four screws 192 (FIGS. 9, 10, 13, 16 and 17) passing through angle plates 194 secured by bolts 196 to the core of the solenoid 95. Between the angle plates 194 and the bracket 185 is a layer of multiple shim material 198 by which the heightwise position of the

solenoid may be adjusted. Beneath the shim material is a lower arm of a U-shaped plate housing member 200 which covers the upper, lower and rearward sides with the exception of an opening 202 (FIG. 16) for passage of the armature 96 of the solenoid. To cover the right, left and forward sides of the solenoid, a second U-shaped plate member 204 is provided, interfitting with the first plate member 200 (FIG. 13) and having flanges overlapping the edges of the first plate member (see FIGS. 9, 13 and 16). To secure the two interfitting plate members releasably together and to the bracket 185, a single screw 206 passes through a slot in an open-slotted tongue on an upper flange of the plate member 204 and a pair of screws 208 pass through similar slots in the lower edge of the plate member 204 and enter into threaded engagement with the outer ends of the projections on the solenoid mounting bracket 185. The forward side of the plate 204 has a clearance slot 210 through which the bar 172 passes, so that the armature and the knife may be moved downwardly by the operator without removing the housing.

The welt end advancing mechanism of the illustrated machine is driven from an auxiliary one-revolution clutch thrown into operation as the machine is being brought to rest at the end of a seam. This auxiliary clutch is set in motion from the driving and stopping mechanism, which in turn is controlled by the treadle 18.

The driving and stopping mechanism of the illustrated machine is substantially the same as that disclosed in United States Letters Patent No. 2,041,945, granted May 26, 1936, upon application of A. R. Morrill, as modified by the construction disclosed in United States Letters Patent No. 2,520,140, granted August 29, 1950, upon application of O. R. Haas. In the machine of these two latter patents, welt gripping and severing mechanisms are provided at the side of the point of sewing operation with the completed stitches of a seam and the gripping and severing mechanism are tripped into operation by a manually exerted pull on the welt when a sewn shoe is withdrawn from operating position in the machine. For this purpose the patented machine is provided with a welt guide roll over which the welt passes toward the sewing point and against which the welt is gripped by a clamp controlled by the driving and stopping mechanism. In the present machine the welt is severed in advance of the point of sewing operation, so that the welt-guiding roll and its gripping clamp are not required.

The driving and stopping mechanisms of the present machine are illustrated in FIGS. 28 to 32. These mechanisms are provided with a high-speed forward driving clutch and a low-speed reversely driving clutch, the driven member of which low-speed clutch is indicated at 212 in FIG. 31 and is splined for sliding movement upon a main sewing cam shaft 214 in the machine. Normally the driven clutch member 212 is held yieldingly disengaged from its driving clutch member and is formed with a hub provided with a cam groove 216 engaged by a roll 217 on one arm of a vibrating bell crank 218 fulcrumed on a fixed vertical shaft 220. The other arm of the bell crank 218 extends over a vertically movable lock pin or bolt 222 (FIGS. 31 and 32) and is formed with a hole 224 arranged to receive the upper end of the lock bolt when the bolt is permitted to rise. The lock bolt 222 is mounted in the central portion of a horizontally movable spring-pressed slide or carrier 226 and is acted upon by a spring 228 surrounding the lock bolt. The spring 228 is compressed between an enlargement at the upper end of the lock bolt and the lower end of a counterbore in the carrier, through which the lock bolt slides. The spring 228 tends to raise the lock bolt into engagement with the bell crank 218. While the machine is in operation the lock bolt is held depressed by connections actuated from the control treadle 18 including a rock shaft 230 (FIGS. 28 and 32) an arm

232 secured to the end of the rock shaft outside the frame 186 of the machine, a roll 234 on the end of the arm 232 and a bell crank 236 rotatable on a cap screw 237 projecting from the frame 186. One arm of the bell crank 236 is provided with a cam surface engaged by the roll and the other arm is pivotally connected to the lower end of the lock bolt 222 by a link 238. While the machine is in operation the lock bolt 222 is held depressed by the connections just described and the bell crank is oscillated idly by the cam groove 216. Upon release of the starting and stopping control treadle to bring the machine to rest the lock bolt 222 is allowed to rise into engagement with the undersurface of the bell crank. At a predetermined point in the rotation of the cam shaft 214 the hole in the bell crank registers with the lock bolt and the lock bolt locks the bell crank to the carrier 226. Continued rotation of the cam shaft 214 causes the low-speed driven clutch member 212 to be moved into engagement with its driving member and thereafter by reason of frictional engagement of the low-speed clutch surfaces the cam shaft is slowed down, stopped and then reversely rotated to a predetermined point at which the clutch surfaces are again separated to permit the cam shaft to come to rest. The cam shaft is thus brought to rest with the needle retracted from the work and the shoe being operated upon freed from the stitch-forming devices, so that the shoe may readily be removed from the machine.

During normal sewing operations the shaft 214 rotates in the direction of the arrow 240 in FIG. 31. At the end of a seam, when the driven low-speed reverse clutch member 212 is moved into engagement with its driving member the sewing shaft 214 reverses its rotation before coming to rest. During the final movement of the sewing shaft a rod 242 mounted within an axial bore of the sewing shaft is moved longitudinally against an arm 244 pivotally mounted to swing within a horizontal plane about a pin 246 (FIG. 28) mounted in lugs projecting from an end plate 248 secured to the frame 186 of the machine. The forward end of the arm 244 is provided with a hook-shaped terminal extending to the left side of an upstanding arm on an L-shaped lever 250 (FIG. 31) fulcrumed on a pin 252 carried by spaced lugs connected integrally with the end plate 248. A horizontal arm of the lever 250 is pivotally connected to the upper end of a link 254, the lower end of which is similarly connected to an arm 256 fixed to the outer end of a shaft 258 rotatably mounted in the frame 186. Within the frame 186 the shaft 258 has secured to it a stop arm 260 forming a part of an auxiliary one-revolution clutch including a shaft 262 rotatably mounted in the machine frame 186. Movement of the stop arm 260 away from the clutch trips the clutch into operation and causes the shaft 262 to be rotated a single revolution. Rotation of the shaft 262 actuates an eccentric on the shaft surrounded by a strap 264, which in turn is pivotally connected to an arm 266 secured inside the frame to a rockshaft 268 rotatable in the frame. Clamped to the outer end of the rockshaft 268 is an arcuately slotted arm 270 within the slot of which is clamped a pivot screw 272 (FIG. 30) at the lower end of a link 274 pivotally connected at its upper end to an arm of a three-armed lever 276 for actuating the welt-end advancing mechanism. To clamp the pivot screw 272 to the arm 270 a thumb nut 273 is threaded on its outer end. Thus, whenever the auxiliary clutch rotates the shaft 262 the welt-end advancing mechanism is actuated. The shaft 262 is rotated and the welt-end advanced by these connections each time the machine is brought to rest at the end of a seam. For sewing sewed heel seat shoes the length of welt advanced by the advancing mechanism is adjusted for less advancing movement than for sewing shoes which are sewn only from heel breast to heel breast.

In the machine of Patent No. 2,900,933 the welt ad-

vancing mechanism comprising an oscillating toothed segment mounted for advancing movement in a forward direction while engaging the welt along a portion supported by a trough-shaped plate. During reverse movement of the toothed segment it has been found that there is a likelihood of retracting the welt or at least disturbing its position into which it was advanced and the trough-shaped plate for supporting the welt against the pressure of the segment requires frequent modification or change in location with changes in styles and sizes of welts operated upon.

In order to avoid displacement of the end of the welt acted on by the welt-advancing mechanism and to render the support for the welt along that portion engaged by the welt advancing mechanism more versatile in use and capable of supporting the welt regardless of style and size, the welt-advancing mechanism of the present invention is provided with a continuously rotatable wheel 278 (see FIGS. 23 to 27 inclusive) and a pressure roll 280 between which the end of the welt severed by the knife 16 is gripped with constant pressure while being advanced (see FIG. 26). For this purpose the roll is mounted for relative yielding movement toward and from the wheel, the connections heretofore referred to between the auxiliary one-revolution clutch and the feed wheel acting both to rotate the feed wheel and to move the pressure roll toward and away from the feed wheel to grip and release the welt.

To enable the feed wheel 278 to adapt itself automatically to any size or style of welt, as well as to cause it to feed the welt more positively than is possible with the oscillating welt-advancing segment of the prior Patent No. 2,900,933, the feed wheel 278 is constructed with bevel cut peripheral welt engaging surfaces 282 (see FIG. 24) forming an angle with its axis of rotation of approximately 40°. The periphery of the roll 280 is constructed with double frusto-conical surfaces, one portion 284 (see FIG. 26) of which forms an angle with its axis of rotation of approximately 40° to cooperate with the surfaces 282 of the feed wheel. At right angles to the portion 284 of the roll 280 is another portion 286 joined to the first portion with their smaller ends together to form a re-entrant right angle fitting the corner of the welt, the 40° angle portion acting to grip the welt against the feed wheel and the other right-angle portion serving as an edge gage for the welt. To provide a clearance area for a bead on a storm welt the roll 280 has a bevel 288 on the outer corner of its 40° portion, as illustrated in FIG. 26, the position of a bead on the welt being indicated by the broken line 290.

The welt advancing wheel 278 is formed with a continuous series of inclined teeth, each tooth having a beveled surface 282 and the teeth being inclined slightly in the direction of the advancing movement imparted to the welt, as indicated by the arrow 292 in FIG. 23. To cause the wheel 278 to rotate continuously it is formed with a hollow hub within which is loosely mounted a roll carrying driver 294 (see FIG. 24) of a one-way clutch secured to a shaft 296 rotatably mounted in one corner of a triangular plate 298 and in the end of an offset arm of a brace 300 secured with the plate 298 to the underside of the guideway portion on the bracket 185 by a screw 302 engaging a threaded opening 304 in the bracket and passing through the plate 298 and the brace 300. To prevent rotation of the brace and the plate about the screw 302 a pair of dowel pins 306 are driven through holes 308 in the bracket 185 and into corresponding openings in the plate 298 and the brace 300, the holes 308 being shown in FIG. 17.

The welt-advancing wheel 278 is rotatable freely on the shaft 296 and is engaged within its hollow hub by a set of spring-pressed rolls 310 (FIG. 23) mounted within the driver 294 of the one-way clutch. To rotate the welt-advancing wheel 278, the rearward end of the shaft 296

has secured to it a forked arm 314 within the fork of which is pivotally connected a lower end of a link 316. The upper end of the link is similarly connected to an arm of the lever 276, the lever 276 having a fulcrum pin 318 secured by a setscrew 320 engaging a flat surface 322 in the pin shown in FIG. 17. The ends of the pin are rotatably mounted in bearings formed in the base and a projection from the guideway 98 of the bracket 185. When the machine is brought to rest at the end of a seam the stop arm 260 of the stopping mechanism is disengaged from the one-revolution clutch to trip it into operation and the lever 276 is oscillated to rotate the welt-advancing wheel 278 and then to return the wheel driver 294 idly without reversing the rotation of the wheel.

After the wheel 278 has completed its welt-advancing rotation the pressure roll 280 is moved away from the wheel to the position shown in FIG. 27, to enable the welt to move toward the sewing point in the machine without resistance. By the use of the one-way clutch for driving the welt-advancing wheel, no difficulty arises from reverse rotation of the wheel before release of the welt from the grip of the pressure roll.

To move the pressure roll 280 toward and away from the welt advancing wheel, the roll is rotatably mounted at the forward end of a bolt 324 clamped by a nut 326 (see FIG. 25) within the lower end of a lever 328 fulcrumed on a threaded stud 330 secured at its forward end within the left lower corner of the triangular plate 298, a shoulder on the stud being clamped against the plate by a nut 332 threaded on the outer end of the stud. The rearward end portion of the stud is surrounded by a torsion spring 334, one end of which is engaged by the lever 328 and the other end of which is bent into a direction parallel to the stud and engages an opening in the nut 336 threaded on the rearward end of the stud, the spring 334 acting to press the pressure roll 280 toward the welt-advancing wheel 278. After the lever 276 is actuated to rotate the welt advancing wheel, a downwardly extending arm of the lever carrying an adjusting screw 338 is moved to actuate an upper arm of the lever 328, moving the pressure roll carrying lever away from the feed wheel against the force of the spring 334. In this position of the pressure roll (FIG. 27) the welt is drawn freely from its source of supply through a U-shaped wire guide 340 by the pull exerted on the welt by the stitch-forming and feeding devices. The wire guide 340 is secured by a setscrew 341 to the lever 328 and the other end of the guide is concealed within an opening of the lever. At the end of the sewing operation the lever 276 moves in a direction to again enable the pressure roll to grip the welt between it and the advancing wheel 278, continued movement of the lever 276 causing the welt to be advanced. During reverse movement of the lever 276 the advancing wheel 278 remains stationary while the shaft 312 and the driver 294 reverse their direction of rotation without driving the welt-advancing wheel, the adjusting screw 338 eventually engaging the upper arm of the lever 328 to move the pressure roll away from the feed wheel and to release the grip on the welt. The welt remains released from the grip of the pressure roll and feed wheel during the time the machine remains idle and until the sewing operation is completed on a new shoe.

To prevent displacement of the end of the welt from proper position to which it is advanced while the machine is idle and to enable the welt to move as freely as possible toward the stitch-forming devices in the machine there is provided a preliminary flanged guide roll 342 (see FIGS. 1, 53, 54 and 55) rotatably mounted on a shoulder screw 344 attached to the downwardly bent end of a metal strap 346 secured to the machine head frame 186 (FIG. 53). The shoulder screw 344 is threaded into a hole in the end of the strap 346 and passes through a slot in an angle plate 348 projecting upwardly from the screw 344 and supporting near its upper end a pivot bolt 350

clamped to the plate 348. Freely rotatable on the shank of the bolt 350 is an antiretraction dog 352 cooperating with the preliminary guide roll 342 to prevent retrograde movement of the welt past the feed wheel when the pressure roll is moved away therefrom, any tension exerted on the welt passing over the guide roll being resisted by the antiretraction dog, which at its lower welt engaging end is provided with a sharpened edge, so disposed as to grip the welt against the roll 342 at a point where the welt is slightly disengaged from the roll, the lower end of the dog extending axially of the roll between the flanges thereon.

To enable a welt having a storm bead, such as that indicated by the broken line 290 of FIG. 26 to be guided by the preliminary guide roll 342, the central area of the roll has a circumferential groove 353 into which the storm bead may fit during its passage over the roll. To enable the antiretraction dog to engage the welt on the roll lightly at all times, the upper end of the dog above the bolt 350 has threaded into it a thumb screw 354 having an enlarged weighted head to overbalance the antiretraction dog. Below the pivot bolt 350 is an adjustable stop formed by a screw 356 threaded into the dog and engaging with its end a flange on the angle plate 348. To limit the movement of the welt engaging end of the dog away from a line connecting the centers of the screw 344 and the bolt 350 and to prevent excessive movement of the welt-engaging end of the dog away from the welt, the upper end of the dog is movable toward and from the end of a thumb screw 358 threaded into a block 360 riveted to the angle plate 348. The thumb screw 358 is formed with a lengthwise groove 362 (FIG. 55) arranged for engagement with a spring-pressed ball 364 mounted in a passageway formed in the block 360 and held in place by a threaded plug 366 (see FIG. 53).

To prevent the welt from becoming twisted and jammed between the preliminary guide roll 342 and to remove kinks from the welt as the welt approaches the guide roll, the strap 346 has clamped to it by the shoulder screw 344 a U-shaped plate 368, the base of the U being cut out to form a pair of slots 370 and 372 (FIG. 53). The slot 370 is cut with a shape to fit extremely wide welts or welts having storm beads and the slot 372 is cut to fit standard flat welts of the type illustrated at 8. To reinforce the plate 368 its two arms have secured between them the arms of a second U-shaped plate 374.

The improved frame constructions for facilitating adjusting, servicing and also for simplifying procedures in assembling the machine of the invention include the arrangement of the bracket 185 on which the welt-severing knife, feeler positioning and welt-advancing mechanisms are removably mounted, the bracket itself being detachably connected to the main frame 186 merely by the removal of the two screws 190 shown in FIG. 28. When the bracket 185 is detached from the machine frame, the mechanisms comprising those for the welt-severing knife, the feeler positioning and the welt advancing wheel 278 comprise a unit, as shown in FIG. 9, the assembled parts of which are independent of and capable of being assembled or adjusted in accurate relationship to each other without reference to the stitch forming, work feeding and guiding devices in the main sewing frame 186. Furthermore, each of the welt-severing knife, the feeler positioning, and the welt-advancing mechanisms may be dismounted from its support on the bracket 185 without disturbing the other mechanisms merely by the removal of a few readily accessible screws, the advantage of such detachable and dismountable construction being readily apparent when it is appreciated that all of these mechanisms, except that for advancing the welt, as well as those for forming stitches, feeding and guiding the work, have devices for engaging the work within a compact area concentrated in a circle of about an inch in diameter, as viewed from the front of the machine. Furthermore, each of the devices acting on the work must be exactly

adjusted and located to cooperate with the other devices in performing a unitary result; namely, of inserting an inseam through a welt, an upper and a sewing rib on the insole of a shoe and automatically locating and severing the welt with a bevel matching that formed on the welt at the leading end first attached to the shoe. Also, it has been found necessary to provide means for overcoming the problem of detaching such unitary assemblage of mechanisms, two of which are electrically controlled and the other of which is mechanically actuated from mechanisms on the main frame of the machine.

To enable convenient detachment of a unitary assemblage of mechanisms actuated partly electrically and partly mechanically, according to this feature of the invention 15 electrical circuits for energizing the knife-actuated sole-noid whenever the feeler is engaged by the leading end of the welt first attached to the shoe, comprise flexible electrical cables 376 and 378 (see FIG. 18) running between a connection box 379 and the knife supporting bracket 20 185 on the one hand, and between the knife-supporting bracket and the feeler base plate 38 on the other hand (see also FIG. 1). The cable 376 includes wires connecting both the knife-actuating solenoid and the feeler actuating solenoid, together with the service wires to the 25 feeler switch and is provided with sufficient length to extend between the knife-supporting bracket when attached to the head frame or when the unitary assemblage of the welt-severing knife, the feeler and the welt-advancing mechanisms on the bracket are laid on the 30 shelf 60, as shown in FIG. 18. It may be desirable to detach the feeler base plate 38 from the knife-supporting bracket 184 and for this purpose the base plate 38 is made fast to a dovetail slide 380 by means of cap screws 382 (see also FIGS. 4 and 5). The dovetail slide 380 is attached to a plate 384 which covers the knife bar guideway 98 on the bracket 185. To attach the slide 380 to the cover plate 384 the slide is engaged in an adjusting guide with its guiding surfaces extending in the direction of feed of the shoe. The adjusting guide is 35 formed by a pair of gib 385 and 388 (see FIG. 6), the gib 388 being screwed directly to the cover plate 384 and the gib 385 having a cap screw 390 passing through it, through the cover plate 384 and into the guideway 98 of the bracket 185.

45 To detach the feeler and its actuating mechanism from the bracket 185 the two screws 382 may be removed or the gib 386 may be dismounted from the cover plate 384 by removal of the cap screw 390. To adjust the position of the feeler 14 and the guard 28 horizontally toward and from its closest approach to the point of operation of the stitch-forming devices to bring it into conformity with the position of the welt severing knife, the cap screw 390 is loosened to free the dovetail slide 380 from the pressure of the gib 385 and the slide is shifted 50 along its guide on the plate 384 (see FIGS. 4 to 7 inclusive). To shift the dovetail slide, a vertically elongated opening 386 (see FIG. 4) is formed in the rearward surface of the slide 380 and projecting through a horizontally elongated opening in the forward surface 55 of the slide is a concentric forward circular portion of an eccentric stud 387, the rearward end of which also is concentric with the forward portion and fits within a passage in the plate 384. The forward projecting portion of the stud 387 is provided with a hexagonal head to 60 assist in rotating it and as it is rotated the eccentric portion moves the dovetail slide 380 along its guide in a manner to adjust the horizontal positions of the feeler and guide. To raise or lower the feeler and guard the cap screws 382 are loosened and the position of the base 65 plate 38 is shifted lengthwise of vertical slots surrounding the screws 382, which at the same time prevent movement of the base plate on the slide in a direction parallel to that of work feed. In other respects the mounting of the feeler and its actuating mechanism are the same 70 as disclosed in inventor's application Serial No. 788,555.

To disconnect the mechanical actuating connections between the welt-advancing mechanism on the bracket 185 and in the main sewing head of the machine, these connections are separated at a single joint between the slotted arm 270 and the lower end of the link 274. For this purpose the pivot screw 272 passes through the ball portion of a universal joint 392 (FIG. 30) at the lower end of the link 274, a washer 394 and the slot, indicated at 396, in the arm 270, the arrangement being such that when the thumb nut 273 is tightened, the screw 272 is secured in adjusted relationship with the slot 396 in the arm 270. If the thumb nut 273 is removed, the parts may be disconnected, so that no impediment remains for separating the unitary assembly of the welt-severing knife, feeler positioning, and welt-advancing mechanisms from the bracket 185.

To dismount the welt-severing solenoid 95 from the bracket 185 it is necessary to remove the four screws 192 (FIGS. 9, 10, 13, 16 and 17). When this is done the solenoid may be dismounted from the bracket 185 for individual adjustment or servicing as required.

The novel work feeding means of the present machine is intimately related to the constructions for facilitating adjustments and servicing of the machine. It is necessary for the welt to be severed at such a position and to be advanced by an amount to bring the end of the welt remaining in the machine into a position exactly related to the point of operation of the stitch-forming devices. As illustrated in FIGS. 2, 34 and 35, the point of operation on a shoe is determined by the relative positions of the needle, indicated at 398, which is of the usual curved hook type for operating on a sewing thread 400 and a curved work piercing awl 402 (see FIGS. 36 and 37), the curvature of the needle defining a plane corresponding with the line XXXV—XXXV in FIG. 34. The awl 402 is also of the curved type and acts to form a perforation for the needle, except in the formation of the first stitch in a seam when the needle penetrates the work without the assistance of the awl, the awl then penetrating the work to provide a perforation into which the needle enters for the formation of the second stitch (FIGS. 36 and 37) and all of the remaining stiches in the seam.

Besides the needle and awl the stitch forming and guiding devices include a needle looper 404 (see FIG. 3), a thread finger 406 acting to form a bight of thread between the work and the looper before the thread is laid in the needle hook, a channel guide 408, a thread truck 410 on a stitch setting take-up 412 (see FIGS. 1 and 58), and a thread tension comprising a wheel 414 against which the take-up acts in setting each stitch, all acting in a manner more particularly described and illustrated in the patents and application above referred to. The tension wheel 414 has applied to it a frictional force produced by a multi-coil spring braking band 415 (see FIGS. 58 and 60) similar to that disclosed in United States Letters Patent No. 2,707,926, granted May 10, 1955, in the name of O. R. Haas.

Not only does the awl engage the work to provide a perforation into which the needle may enter but also with the needle the awl acts to move in the direction of work feed with the needle, sometimes while in laterally spaced relation thereto and sometimes in alinement therewith, each acting alternately to impart a continuous feeding movement to the work. At the time the machine is in a normally stopped position to which it is brought by the driving and stopping mechanisms, both the needle and awl are disengaged from the work, the needle being in a position where it is about to enter the work during the next rotation of the cam shaft 18. At this time the planes defined by the needle and awl have a lateral space between them, as shown in FIG. 36. It is within the lateral space between the needle and awl planes that the welt-advancing mechanism must locate the leading end 12 of the welt severed by the knife 16, with such precision that the needle 398 does not engage it but that the awl 402

will, it being desirable not to subject the needle regularly to the duty of forming its own perforation through the welt during sewing operations. Furthermore, it is highly desirable that the thread in the first formed stitch of a seam be carried across the leading end 12 of the welt in order to prevent its displacement and to secure it rigidly in position where it may be engaged reliably and accurately by the feeler 14. The first stitch of each seam being inserted with threads crossing the end of the welt 8 prevents any displacement of the welt, as illustrated in FIGS. 38 and 39 and insures accurate matching of the final end of the welt with that first attached to the shoe. The result is that the security of attachment for the welt is considerably enhanced, particularly when it is realized that all of the stitches are inserted with a single unbroken strand of thread running from the first stitch entirely about the shoe and returning across the matched and butted ends of the welt in the last few stitches of the seam. Thus, at the end of a seam the welt is severed by the knife 16 and the welt-advancing mechanism is actuated to bring the leading end of the welt into such position with relation to the point of sewing operations, that when the machine is restarted the needle will penetrate the upper 4 and the sewing rib on the insole 2 to the exclusion of the welt 8, as shown in FIGS. 34 and 35 during the formation of the first stitch in a new seam. After the needle 398 has penetrated the upper and rib and has retracted with a loop of thread 400, as shown in FIGS. 36 and 37, the awl 402 also penetrates the work, including the welt 8. After retraction of the awl the work is fed to such a point that the needle during its succeeding work-penetrating stroke enters the perforation formed in the work by the awl, as shown in FIGS. 38 and 39. In entering the awl perforation in the work the needle, which already is carrying in its hook a loop of thread 400 drawn from the perforation in the upper and rib only, lays that loop across the leading end 12 of the welt 8 where it is tightened by the take-up about the shank of the needle. During the second and each succeeding retracting stroke of the needle it withdraws a loop of thread through the previous loop and tightens the previous loop still further with the assistance of the take-up, to set the loop securely with a stitch-setting tension. These results are obtained in accordance with the present invention entirely automatically and without any attention on the part of the operator of the machine.

Referring to FIGS. 40 to 44, inclusive, it will be seen that novel and compact mechanisms comprising sets of connections for imparting to the needle and awl their work-engaging and feeding movements have been provided. Both the mechanisms for actuating the needle and awl toward and from engagement with the work are driven from individual grooves 416 and 418 formed in opposite sides of a single cam 420 and for imparting feed movements to the needle and awl, a single cam 55 groove 422 is formed in the periphery of a cam 424 (FIG. 40), both cams 420 and 424 being secured to the sewing shaft in proper angular relation by a keyway and a key 426.

To actuate the needle 398 toward and from the work 60 the cam groove 416 (FIG. 41) has engaging it a cam follower roll 428 rotatably mounted at the rearward end of a lever 430. The lever 430 is fulcrumed on a shaft 432 having its ends fixed in the frame 186 of the machine. The forward end of the lever 430 is pivotally connected to a link 434, also pivotally connected to a needle segment or carrier 436 mounted to oscillate with the needle and to move in the line of feed with the needle in the frame of the machine, as disclosed in United States Letters Patent No. 1,971,575, granted August 28, 70 1934, upon application of A. R. Morrill. The awl also is actuated toward and from the work by the cam groove 418 through its engagement with a cam follower roll 438 (FIG. 42). The roll 438 is rotatably mounted on an upstanding arm of a lever 440 fulcrumed on the shaft 75 432 and is pivotally connected at its forward end through

a link 442 to an awl segment or carrier 444 (see also FIG. 44). The segment 444 is pivotally mounted for movement of the awl toward and from engagement with the work by means of stub shafts 446 and 448 integral therewith. The stub shafts are journaled in bearings in the frame 186 for rotational and lengthwise movement in the direction of work feed, as disclosed in United States Letters Patent No. 1,920,998, granted August 8, 1933, upon application of A. R. Morrill.

Instead of employing two feed levers acting on the ends of the stub shafts 446 and 448 at opposite ends of the awl segment, as in the machine of the prior patent, the left-hand stub shaft 446 of the present machine is formed with an axial bore and is slotted to receive the forward rounded end of a feed lever 450, the bearing in the frame engaging the stub shaft 446 being similarly slotted to clear the feed lever 450. Engaging one side of the rounded end on the feed lever is a lost motion adjusting screw 452 threaded axially into the stub shaft and surrounded by a check nut 454 for locking the screw 452 in adjusted position. At the other side of the rounded end on the feed lever 450 is a disk 455 seated on a shoulder within the bore of the stub shaft 446 provided by a reduction in diameter. By means of the adjusting screw 452 and the disk 455 movement of the feed lever imparts a to-and-fro motion to the awl segment in the direction of work feed.

The needle segment 436 is best illustrated in FIG. 43 and its construction has been improved over that in Patent No. 1,920,998. The present needle segment 436 is formed integrally with a sleeve 456 which surrounds a shaft 458 at one side of the segment and at the other side of the needle segment the shaft 458 is engaged by a channel guide carrier 460 having an integral hub rotatable and slidable axially in one of a pair of aligned bearings in the head frame 186, in the other of which bearings the sleeve 456 and an enlarged head on the shaft 458 are similarly rotatable and slidable. To prevent the displacement of the parts along the shaft 458, its right end is provided with a threaded opening into which is engaged a screw 462 carrying a washer 464 engaging the sleeve portion of the channel guide carrier 460, the channel guide 468 being secured to the carrier 460 by a screw 466 passing through the channel guide and into the carrier 460.

Instead of employing two feed levers acting at opposite sides of the needle segment 436, as in the machine of Patent No. 1,920,998, the shaft 458 in the present machine is formed with a diametrical slot into which enters the rounded forward end of a feed lever 468 and the rounded end is engaged with one edge of the slot in the shaft 458 and at the other side of the rounded end by an adjusting screw 470 threaded axially into the shaft 458 and secured in adjusted position by a check nut 472. By adjusting the screw 470 all looseness may be taken out of the connection between the shaft 458 and the rounded end of the lever 468. Also rotatably mounted in the channel guide carrier 460 is a shank portion of the thread finger 406, as in the machine of Patent No. 1,920,998.

To actuate the needle and awl feed levers 468 and 450 they have mounted at their rearward ends a pair of follower rolls 474 and 476 (see FIG. 47), engaging angularly disposed portions of the cam groove 422 (FIG. 40).

Instead of utilizing means for adjusting the length of feeding movements of the needle and awl segments through the use of slotted actuating arms in the connections for producing the movement to the respective parts, the illustrated machine is so constructed that only the fulcrums for the needle and awl feed levers 468 and 450 need be shifted by a relatively simple manipulation, the connections themselves remaining otherwise unaffected. Also, the fulcrums are so constructed that a continual flow lubrication system is conveniently arranged for effec-

tive use with any adjustment of the feed mechanisms. To these ends the fulcrums for the needle and awl feed levers consist of a pair of pivot pins 478 and 480, each engaged with one of a set of multiple fulcrum bearings in each lever, the fulcrum bearings in the needle feed lever being indicated at 482 and 484 in FIGS. 50 and 51 and the fulcrum bearings in the awl lever being indicated at 486 and 488 in FIGS. 44 and 45. To support the fulcrum pins for the needle and awl levers they are engaged in sets of bores formed in a yoke 490 (see FIG. 52), secured to the frame 186 of the machine by bolts, one of which is shown at 492 in FIG. 3 and dowel pins, one of which is shown at 494 running through the yoke and the frame. The needle lever pin engaging bores are indicated at 495 and 496 and the awl lever pin engaging bores at 497 and 498 (see FIG. 52) in the yoke 490.

In order to insure that the needle will always enter a perforation in the work formed by the awl regardless of the locations of the pivot pins 478 and 480 in the bearings of the levers and the bores in the yoke, the locations of the bearings and bores not engaged by the pivot pins are spaced in proper relationship to bring all the respective bearings and bores into register at that time in each sewing cycle while the needle is entering the work, the connections otherwise being adjusted to insure alignment of the needle with the perforation formed in the work by the awl. At other times during each sewing cycle the bearings and bores not engaged by pivot pins are necessarily moved out of aligned relationships.

When the awl lever pivot pin 480 is in the uppermost bearing 488 of the feed lever 450 and the corresponding bore 497 of the yoke 490, as shown in FIGS. 45, 47 and 48, and the needle feed lever pivot pin 478 is in its rearmost bearing 482 and the rearmost bore 496 of the yoke 490 as in FIGS. 45, 47 and 50, the machine is capable of forming the longest stitches, of which three and one-quarter occupy an inch of seam. With the awl lever pivot pin 480 in the same uppermost position, as in FIGS. 45, 47 and 48, but with the needle pivot pin in 478 moved to the most forward bearing 484 and corresponding bore 495 (FIG. 51), a seam will be inserted in which three and five-eighths stitches constitute an inch. If the awl pivot pin is moved to its lowermost bearing 486 and bore 498 in the yoke 490 (FIG. 49) and the needle pivot pin 478 remains in its most forward bearing 484 (FIG. 51) and bore 497 in the yoke 490, the shortest possible stitches will be inserted, in which four complete stitches will constitute one inch of seam.

The pin 478 enters the bores 495 and 496, each of which consists of two aligned parts formed in spaced portions of the yoke 490 and the pin is secured in place by a setscrew 499 (see also FIG. 3) engaged with a flat surface on the pin 478. For convenience in shifting the position of the pin 478 the screw may be engaged in either of two threaded holes 500 in the yoke 490 (see also FIG. 52). To retain the awl feed lever pivot pin in position within the yoke 490 the lower end of the pin is threaded and engages corresponding threads in the bores 497 and 498.

For introducing a continuous flow of lubricant into the bearings of the levers during operation of the machine with any adjustment of the feed mechanisms, the pivot pin 480 has an axial passageway 501 (FIGS. 44, 45 and 47) and a set of radiating passageways 502 terminating inside the bearing 488 of the lever 450. Entering the passageway 501 is a lubricant supply tube 503. At their lower ends the bores 497 and 498 for the awl lever pivot pin 480 are connected by ducts 504 and 505 extending vertically downwardly into the bores 482 and 484 for the needle feed lever pivot pin 478 (see FIG. 45). In this way lubricant introduced into the awl lever pivot pin 480 is carried through one of the ducts into the bore for the needle lever pivot pin. To distribute the oil introduced into the bore for the needle lever pivot pin 478, the pivot pin has an axial passageway 506 (FIG. 45)

extending part way into the upper end and communicating with radiating pasageways 507 running inside the bearing of the lever 468. When the pin 480 is in the uppermost bore 497, and the pin 478 is in the rearward bore 496, as shown in FIG. 45, lubricant will flow through the passageway 501 in the pin 480, through the duct 504 and into the passageway 506 in the pin 478 where it will be distributed through the radiating passageways 506. If the pins are disposed in bores of the yoke 490, which are not directly connected by ducts 504 or 505, a plug in the form of a screw 508 is inserted in the bottom end of the pin 480 and is threaded into the lower end of the passageway 501, as shown in FIG. 46. When the screw 508 is used to plug the end of the passageway 501, the lubricant takes a path formed by auxiliary radiating passageways 510 in the pin 480, through a channel 512 connecting the bores 486 and 488 and into the opposite duct, so that lubricant may be provided for the bearing surfaces engaging the needle lever pin 478 under these conditions. When the plug screw 508 is removed the lubricant flows freely through the lower end of the passageway 501, only a small proportion passing through the radiating passageways 510. Thus, the plug prevents flow of lubricant between the bore for the awl lever pin 480 and a bore of the yoke in which the needle lever pin 478 is omitted.

For convenience in mounting the welt guide mounting bar 110 the yoke 490 (see FIG. 52) has downwardly extending bearing lugs 513, in which are secured a pair of aligned pins 515 engaging loosely within openings of an inverted U-shaped swinging link 516. Running between the lower ends of the link 516 and through a midportion of the bar 110 is a pin 518 secured within the bar by the engagement of a setscrew 519 threaded into the bar. The rearward end of the welt guide bar 110 is otherwise connected to mechanism and actuated in a manner more fully disclosed in Patent No. 2,647,478 above referred to.

To sever the thread from a shoe at the end of a seam and to insure that the first stitch of a new seam is properly formed, it has been the practice to equip machines of the type herein illustrated with a thread cutter and a frictional thread end holder generally similar to that employed in United States Letters Patent No. 2,492,147, granted December 27, 1949, upon application of Dana P. Hay. In the use of such thread cutter and end holder of the patent, after each sewing operation on a shoe is completed the shoe is removed from the machine, withdrawing a length of thread connecting the end of the seam in the shoe with the looper, and the shoe is given other movements to carry the thread into the grip of the holder and against the edge of the thread cutter. The frictional thread end holder, as shown in FIG. 3, consists of a pair of yielding gripping jaws 520 and the thread cutter consists of a knife 521. The gripping jaws 520 are formed by a pair of horizontal elongated plates having flaring spaced ends between which the thread is drawn before engaging the knife. The jaws and knife are secured directly to the machine frame 186 by means of a clamping screw 522 passing through the jaws and knife into the frame 186, a screw 523 serving to attach the inner jaw 520 only to the frame. When held in the gripping jaws 520 the thread is retained in a position ready for engagement with the thread finger and will release the thread readily under tension while a succeeding loop is being drawn through the work by the needle.

In the use of the thread cutter and thread end holder the thread remaining in the machine, after being severed at the end of a seam, extends from the holder as shown in FIG. 62 through a bight formed on a thread finger 524 and into a looper 525. As the prior machine is being started to insert the first stitch of a new seam in a shoe as shown in FIG. 62, there is a likelihood that the end of the thread, indicated at 526, will become disengaged from gripping jaws 520, shown in FIG. 62. As the looper 525 begins to move it first forms a bight of thread on the thread finger and then starts to move about the hook of

a needle 527, the thread being drawn over a stationary thread truck 528 by the looper and a take-up 530 against the action of a tension wheel 532 to apply sufficient tension on the thread to lay it in the needle hook. If the tension is too great or the grip on the thread end 526 is too weak there is a chance that the thread may be pulled free of the gripping jaws, as in FIG. 63. Even if it is laid in the needle hook the end 526 may be withdrawn with the needle through the work, so that the proper formation of the first stitch is not completed and quite likely the stitch will remain loose and ineffective in its holding power. Until the third or fourth engagement of the needle with the work there thus may be no completely tightened stitch inserted, as illustrated in FIG. 64. In order to insure that the first stitch of a new seam inserted by the present machine is securely tightened against the work while the loop forming the stitch still surrounds the shank of the needle 398 and extends across the end of the welt in the position to which the welt is advanced before the machine is started, as in FIG. 67, limited slack thread means is provided. The limited slack thread means is connected for actuation at the end of a seam by the driving and stopping mechanisms for measuring an amount of thread from the thread tension wheel 414 and for giving up the measured amount of thread beginning with the position of FIG. 65, while the thread finger 406 is forming its bight of thread between the gripping jaws 520 and the looper 404 and before the looper lays the thread in the hook of the needle 398. In this way, the thread end 526 is detained in position by the gripping jaws 520, as shown in FIG. 66, while the thread is being laid in the hook of the needle. However, the limited slack thread means provides insufficient thread to leave an excessive length extending from the work in the first stitch of the seam, as may occur with the prior machine. Thus, the first stitch of a seam is securely tightened with certainty and the end 526 extends not over an inch and a half from the shoe, as shown in FIG. 67. Besides preventing looseness in the first stitch the measured slack thread means prevents wastage of thread and avoids the necessity of trimming the thread end at the beginning of the seam. The necessity for trimming the thread end at the beginning of a seam is readily apparent when it is appreciated that the end 526 in FIG. 64 may not be carried through the work at all by the needle during the formation of the first stitch, but an empty perforation only will be produced, the thread not having been engaged with the needle hook during its first work penetrating stroke, and an amount of thread corresponding to that between the end 526 and the second stitch, as illustrated in FIG. 64 extending loosely from the second stitch of the seam.

The limited slack thread measuring means is best shown in FIGS. 58 to 61, inclusive, and comprises a thread truck 534 over which the thread passes between the tension wheel 414 and a second thread truck 536 mounted on the lower arm of a thread tension responsive lever 538. From the truck 534 the thread extends beneath the truck 536 to the take-up truck 410 and through the looper 404 to the last formed stitch in the work. The truck 534 is rotatably mounted and provided with a thread guard 540 on an arm 542 clamped to a shaft 544 rotatably mounted in a support bracket 546, which also has bearings for a shaft 548 forming the fulcrum for the take-up 412. The arm 542 extends along the right side of the bracket 546 and at the left side of the bracket the shaft 544 has secured to it an arm 550 provided with a hooked upper end engaged by a spring 522 stretched between the arm 550 and a plate 554 (FIG. 60) made fast to an upstanding arm of the bracket 546. The action of the spring 522 is to move the thread truck 534 downwardly and away from the thread running between the tension wheel and the thread truck 536. At the end of a seam as the machine is coming to rest during reverse rotation

of the sewing cam shaft 214 (FIG. 41) the driving and stopping mechanisms cause a thrust to be exerted on a rod 556 (FIG. 58) in an upward and forward direction to bring it against a button at the lower end of an adjusting screw 558 threaded into a C-shaped arm 560. The arm 560 is pinned to one end of a rockshaft 562 rotatably mounted in the bracket 546. The other end of the rockshaft 562 has pinned to it an upstanding arm 564 engaging at its rearward side with a roll 566 rotatably mounted in a recess of the arm 560. The arrangement is such that when the rod 556 is pressed upwardly against the adjusting screw 558 the shaft 562 is rocked in a clockwise direction as shown in FIG. 58, causing the arm 560 to be moved in a similar direction together with the shaft 544, the shaft 544 moving the slack thread arm 542 in a direction to measure thread from the tension wheel by increasing the path of the thread running from the tension wheel to the thread truck 536.

After measuring the thread, the slack thread measuring arm 542 retains its position until the machine is started in operation at the beginning of a new seam in a shoe. As the machine is started in operation and while the thread finger is drawing out its bight of thread between the gripping jaws 520 and the looper, as shown in FIG. 65, but before the looper lays the thread in the hook of the needle the push rod 556 is retracted permitting the slack thread arm to be rotated in a counterclockwise direction under the action of the spring 552 so that the measured thread will be rendered available to the other stitch-forming devices. With proper adjustment of the screw 558 the exact amount of thread required to form the first stitch of a new seam will be given up by the slack thread arm 542, so that the thread end 526 will not be retracted from the gripping jaws 520, but will be retained as illustrated in FIG. 66 until the needle retracts into the work with the loop of thread in the first stitch of the seam, thus producing a uniform and accurate formation of the first stitch of the seam.

In order to avoid the possibility of severing the welt as a result of an emergency stop rendered necessary by improper formation of stitches after the safety relay K1 has been energized, the illustrated machine is provided with mechanism for opening the circuit of the feeler switch 94 whenever the take-up fails to tighten a stitch with a predetermined tension regardless of whether tension failure is a result of improper stitch formation from thread or needle breakage or from other cause. To this end the lever 538 carrying the truck 536, beneath which the thread passes from the thread measuring truck 534 to the take-up truck 410, comprises a yielding thread tension safety member and is secured to a horizontal shaft 568 rotatably mounted in the supporting bracket 546. Above the shaft 568 the lever 538 has an upstanding arm into which is threaded a screw 570 (FIG. 33) having a perforated forward end engaged by a spring 572 also connected at its opposite end in the plate 554 (see FIG. 60). The action of the spring 572 is to rotate the lever 538 yielding in a counterclockwise direction as viewed in FIG. 58 and to engage the thread extending between the thread measuring truck 534 and the take-up truck 410, as illustrated in FIG. 58. To limit the movement of the thread-engaging truck 536 the lever 538 has threaded into it an adjustable stop screw 574, engaging a portion of the bracket 546. During the normal operation of the machine as the take-up applies a stitch setting tension to the thread, the truck 536 is raised by thread tension swinging the tension responsive lever 538 in a clockwise direction about the axis of the shaft 568, raising the adjusting screw 574 from engagement with the bracket 546.

When the tension responsive lever 538 is rotated in a clockwise direction it is locked in the position to which it is raised at all times except while each stitch is being set, by a latch 576 comprising a segmental plate rotatable on a cross shaft 578 secured in an upstanding portion of

the supporting bracket 546. The latch has a split hub surrounding a sleeve portion of a forwardly extending arm 580 carrying a roll 532, the split hub on the latch being clamped to the sleeve portion of the arm and the arm being rotatable on the cross shaft 578. The roll 532 engages a cam plate 584 (see FIG. 33) made fast to the take-up 412, so that as the take-up rises to take thread, the roll 532 moves from the position of FIGS. 33 and 61 to that of FIG. 58. When the latch plate is in the position of FIG. 61, a latching surface 586 on the plate engages a stud 588 threaded into an opening 590 (see FIG. 59) in the lever 538 and provided with a check nut 592 for securing the stud in place. When the surface 586 engages the stud 588 the tension safety lever 538 is locked in a position in which an adjusting screw 594 in the upper arm of the lever 538 actuates a roll 596 mounted on a plunger 593 of a normally open switch 4LS (FIG. 61) mounted on the supporting bracket 546, the screw 594 being adjusted to cause the switch 4LS to be opened upon loss of thread tension when the lever 538 is not locked or held by the tension in the thread in raised position by the latch plate 576. To prevent damage to the switch 4LS the upstanding arm of the lever 538 has threaded into it a stop screw 602 which is arranged to engage a right-angle portion of a plate 604 (FIG. 58) clamped to the bracket 546.

The thread tension responsive lever 538 is only unlocked at a time in each sewing cycle when the take-up is in its stitch setting position shown in FIG. 58. When in this position the cam plate 584 raises the roll 532 and swings the latching surface 586 away from the stud 588. At all other times the latch 576 is urged toward a tension lever locking position, as in FIG. 61 by a torsion spring 606 (FIG. 60) coiled about the end of the shaft 578 and engaging at one end a slot in a disk 610 secured to the end of the shaft by a screw 612. The other end of the spring 606 is made fast to a pin 607 (FIG. 61) in the bracket 546, the spring acting to rotate the latch plate 576 and the arm 580 in a counterclockwise direction toward the take-up 412.

To insure that the roll 532 will follow the giving-up movement of the take-up 412 the cam plate 584 has an upstanding projection 614 beneath which the roll 532 moves while the take-up 412 is applying a stitch setting tension to the thread. As soon as the take-up begins to give up thread the projection 614 actuates the roll 532 positively to start its downward movement, causing the latch plate 584 to be moved beneath the stud 588. If, however, the thread is broken or the tension is lost during the upward stitch setting movement of the take-up 412 and the thread truck 536 is allowed to move downwardly to the position shown in FIG. 58, the stud 588 is lowered into a depression at the lower end of the latching surface 586. In this position of the lever 538, the roll 532 may move upwardly away from the path of the take-up a sufficient distance to escape the projection 614 on the cam plate 584. Accordingly, the adjusting screw 594 having been disengaged from the switch actuating roll 596, the circuit through the feeler-actuated switch 94 (see FIG. 68) is opened and the welt-severing knife will not be actuated when the stopping mechanism brings the machine to rest for correction of the maladjustment which caused the loss of thread tension.

In order to insure that the machine will continue in operation and insert a predetermined number of stitches after the welt has been severed in sewing either a sewed heel seat shoe or a breast-to-breast sewn shoe, the driving and stopping mechanisms of the illustrated machine are provided with counting mechanism which acts to prevent engagement of the lock bolt 222 with the vibrating bell crank 218, until the desired number of stitches have been inserted. When the control treadle 18 (FIG. 1) is depressed to start the machine in operation, the lock bolt 222 (FIG. 32) is retracted from the hole 224 in

the bell crank 218 through a rearwardly extending arm of the lever 164 (FIG. 1). For this purpose the arm of the lever 164 is pivotally connected through a short vertical link 616 (FIGS. 1 and 32) with an arm 618 secured to the rockshaft 230.

The counting mechanism is shown in FIGS. 28, 31 and 32 and includes a clamp block 620 secured to the lower end of the lock bolt 222 and formed with spaced bearings within which is rotatable a pin 622 also passing through the hub of a counting finger 624. The upper end of the counting finger is formed with a notch 626 arranged to engage the lower forward corner of a block 628 secured to the extreme end of the vibrating bell crank 218. Below the notch 626 the counting finger has a group of two detent surfaces 630 and 632 disposed to engage a block 634 secured to one side of the lock bolt carrier 226. A laterally extending arm of the counting finger 624 is connected to one end of a tension spring 636, the other end being connected with a pin 638 projecting from the lower surface of the clamp block 620. The spring 636 tends to hold the counting finger in engagement with the forward surfaces on either one of the blocks 628 and 634.

Referring to FIGS. 31 and 32, when the control treadle 18 is released to bring the machine to rest, the counting finger 624 moves to a position beneath the block 628 against which it rises. Engagement of the counting finger 624 beneath the block 628 prevents the lock bolt 222 from entering the hole 224, so that the bell crank continues to vibrate, moving the forward edge of the block 628 rearwardly beyond the end of the finger, the counting finger being held from movement with the block 628 by the engagement with the block 634. As soon as the block 628 has moved beyond the end of the counting finger 624, the detent surface 630 engages the under side of the block 634, so that the lock bolt 222 is still held from entering the hole 224 in the bell crank 218. Continued oscillation of the bell crank 218 causes the lower corner of the block 628 to enter the notch 626 in the counting finger and continued movement of the block 628 moves the counting finger away from the block 634, so that the counting finger and lock bolt 222 now rise until the lower front corner of the block 634 moves away from the detent surface 630. These movements of the vibrating bell crank 218 represent a complete sewing cycle and the formation of a single stitch in the work after the treadle 18 has been released. Upon a second rearward movement of the bell crank 218 the block 628 is moved rearwardly and the counting finger moves with it until the vertical riser between the detent surfaces 630 and 632 engage the lower forward corner of the block 634. When this occurs the block 628 continues to move while the counting finger remains stationary and the counting finger is released for a second short upward movement, the lock bolt 222 still being held out of engagement with the vibrating bell crank 218. During the next forward movement of the vibrating bell crank 218 the block 634 engages the detent surface 632 until the counting finger is engaged by the block 628. At this time the detent surface 632 is moved away from the block 634, so that the lock bolt now rises into engagement with the bell crank 218. However, at this time the lock bolt still does not register with the hole 224, so that it is not until the return rearward movement of the bell crank that the lock bolt enters the opening. The machine is then brought to rest after inserting a second stitch crossing the severed ends of the welt and the shaft 214 is rotated in a reverse direction until the stopping position is reached.

In the machine of Patent No. 1,971,575 the lock bolt carrier, corresponding to the presently illustrated carrier 226, is held yieldingly in a rearward position by a compression spring surrounding a rod extending from the forward end of the lock bolt carrier, the spring being interposed between a shoulder on the carrier and the rear-

ward end of a screw threaded sleeve through which the carrier passes. The forward end of the sleeve is threaded to receive a pair of adjusting nuts which engage the outer end of the sleeve to hold the spring under compression.

5 The purpose of these adjusting nuts is to enable the force of the spring to be changed in accordance with the wear of the parts in the machine and especially with the wear of the frictional surfaces on the reverse driving clutch corresponding to that indicated herein at 212 (FIG. 31). 10 When the parts of the machine have become well worn it is possible for an operator to adjust the prior spring compressing nuts on the carrier rod until there is insufficient space between the coils of the spring to enable a full stroke of the vibrating bell crank when locked to 15 the carrier 226. Accordingly, there is danger that the parts of the machine will become broken and that at best the stopping mechanism will be subjected to excessive forces for which it was not intended.

To avoid the possibility that an operator will adjust 20 the compression of the lock bolt carrier spring in the present machine, as shown in FIGS. 28 and 29 at 640, this spring is mounted within a hollow cylinder 642 secured to the machine frame 186 in a position extending to the rear of the machine rather than forwardly, as in the machine of the prior patent, and a rearwardly extending rod 644 attached to the lock bolt carrier 226 passes through the cylinder and has at its most rearward end a threaded portion engaged by an internally threaded thimble 646 and a check nut 648. The spring 640 is compressed between the forward end of the cylinder 642 and the thimble 646, and the rearward end of the cylinder is internally threaded to receive a threaded sleeve 650 engaging a shoulder on the forward end of the thimble. If an attempt is made to compress the spring 640 by 25 adjusting the thimble along the carrier rod 644, the rod will be drawn rearwardly until the thimble engages the forward end of the sleeve 650 and thereafter no further compression will be imparted to the spring. If an attempt is made to compress the spring by adjusting the 30 threaded sleeve 650, the alignment of the lock bolt 222 with the hole 224 in the bell crank 218 will be disturbed, so that proper functioning of the stop mechanism will not occur. In order to prevent adjustment of the sleeve 650 beyond the point where the spring will be compressed to such an extent that the coils come into contact, the hollow cylinder 642 is formed with an internal shoulder 652 (FIG. 28) of smaller diameter than the threaded sleeve 650, so that as the sleeve is adjusted inwardly of the cylinder it will eventually engage the 35 shoulder and prevent compression of the spring beyond the safety point of contact between its coils. Under normal operating conditions the rod 644 is drawn forwardly while the machine is being brought to rest and the spring 640 is compressed momentarily to the position 40 of FIG. 29. With the present construction there is no danger that the spring 640 will be compressed to such an extent that the coils will come into contact or that parts will be subject to breakage.

Referring further to the wiring diagram of FIG. 68, 45 it is highly desirable for safety reasons to avoid operation of the welt-severing solenoid while the machine is in stopped position. Accordingly, there is connected to the main line switch 86 a normally open secondary line switch LS1 (see also FIGS. 60 and 61) having a plunger 654 on which is mounted a roll 656 at a position to be engaged by the arm 564 during normal sewing operations, the arm 564 being actuated by engagement of the roll 566 (see also FIG. 58) on the arm 550, which in turn is moved forwardly by the spring 552. At the end 50 of a seam when the machine is brought to rest the stopping mechanism rod 556 engages the adjusting screw 558 and moves the arm 564 rearwardly away from the roll 656 on the switch LS1 to disconnect the supply line 84 from all of the electrical circuits, including the transformer 138.

The slack thread provided by the measuring device 542 does not affect the operation of the thread tension responsive lever 538 at the beginning of a seam, since the circuit to the safety relay K1 is held open by the switch LS3 and the welt severing solenoid cannot operate at this time. Also, the counting mechanism connected with the stopping mechanism is effective both for the operation on sewed heel seat shoes and for heel breast to heel breast sewn shoes, since in both instances it is desirable to continue the sewing operation until after the welt is severed. In a sewed heel seat shoe the purpose of continuing the sewing operation is to insure that stitches will be inserted across the matched and butted ends of the welt. In a heel breast to heel breast sewn shoe, it is desirable to continue the sewing operation in order to attach the final end of the welt on a shoe without leaving an excessively long unattached portion which requires trimming and wastage.

All of the features of the invention as above described are cooperative to produce a unitary result, especially when employed together in the circuit, as outlined. For instance, the welt-severing mechanism is operative through different circuits with the selector switch 144, 156, 154 in either of its actuated positions S—S or B—B for sewing sewed heel seat shoes or for sewing heel breast to heel breast sewn shoes. While the feeler 14 is rendered inoperative in sewing heel breast to heel breast sewn shoes, it is out of operative position and is incapable of closing the switch 94, so that no danger from improper operation of the welt-severing knife then is possible.

Partly by way of review and partly in order to obtain a better understanding of the electrical system, with further reference to FIG. 68, it will be seen that the circuit supplied by the secondary line switch LS1 is divided into two parallel portions, one through contacts K1C and the uppermost element 154 of the selector switch, on the one hand, and the switch LS2 on the other hand. Both parallel portions then are joined together and conduct current through the contacts K2A forming a part of the knife releasing relay K2, which is energized a predetermined time after the feeler contacts 94 have been closed. Until the treadle 18 is released at the end of a seam the switch LS2 remains open and no current flows through the safety relay K1. As soon as the safety relay K1 is energized, contacts K1C and K1A are closed, continuing the energization of the safety relay until the circuit is opened by the contacts K2A. With the selector switch handle 152 in the "SS" position shown, the contacts K1C have no function because the circuit through these contacts is opened by the element 154 of the selector switch while operating upon sewed seat shoes. If heel breast to heel breast shoes are to be operated upon, the element 154 in the selector switch is closed and the current continues to flow through the safety relay regardless of the position of the switch LS2 so long as the contacts K1C remain closed.

When the selector switch handle 152 is in the "SS" position, the switch element 144 is also in the "SS" position, so that the feeler switch 94 is connected in circuit with the supply line through the transformer 138. When, however, the selector switch handle is in the "BB" position, the element 144 disconnects the feeler switch 94 and connects the treadle controlled switch 6LS in circuit with the knife actuating relay, so that whenever the treadle 18 is released to bring the machine to rest, the welt is severed. Also, when the treadle 18 is released to bring the machine to rest, the switch LS2 is caused to close to complete the circuit to the welt-severing solenoid and to connect either the feeler switch 94 or the treadle-controlled switch 6LS to the power line 86 through the transformer 138.

In order to enable easy reference to the foregoing specification, particularly in connection with the circuit

diagram designations, the following tabulation of non-numerical reference characters will be found useful:

5	Element	Part Designation	First Appears After Reference Numeral
10	Position	BB	152

The invention having been described, what is claimed is:

- 25 1. An inseam sewing machine for attaching a welt to a last-supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife including a solenoid and an armature connected to the knife, a feeler for engaging the leading end of the welt already attached to the shoe as that end approaches the stitch-forming devices a second time, and
- 30 35 a shiftable carriage on which the feeler is mounted for movement toward and from an operating position with relation to the shoe, in combination with a feeler positioning solenoid connected to the shiftable carriage for moving the feeler toward the shoe and a solenoid energizing circuit including a safety relay connected to prepare the circuit for actuation of the feeler positioning solenoid for holding the feeler in operative position with relation to the shoe.
- 40 45 2. An inseam sewing machine for attaching a welt to a last-supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife including a solenoid and an armature connected to the knife, a feeler for engaging the leading end of the welt already attached to the shoe as that end approaches the stitch-forming devices a second time, and
- 50 55 a shiftable carriage on which the feeler is mounted for movement toward and from an operating position with relation to the shoe, in combination with a feeler positioning solenoid connected to the shiftable carriage, and means displaceable by the operator for energizing the feeler positioning solenoid to move the feeler toward the shoe and to hold the feeler in operative position with relation to the shoe.
- 60 65 70 75 3. An inseam sewing machine for attaching a welt to a last supported Goodyear welt shoe upper and a sole member, said machine having stitch-forming, feeding and guiding devices for the shoe parts, a welt-severing knife mounted for movement toward and from the welt as it passes through the guiding devices, mechanisms for actuating the knife including an actuating solenoid and an armature connected to the knife, a feeler for engaging the leading end of the welt already attached to the shoe as that end approaches the stitch-forming devices a second time, a shiftable carriage on which the feeler is mounted for movement toward and from an operating position with relation to the shoe, yielding means for restraining the carriage in a position in which the feeler is held away

from operating position with relation to the shoe, an operator displaceable lever and a pad on said lever disposed at a position convenient for engagement by the leg of the operator, in combination with a feeler positioning solenoid connected to the shiftable carriage, a switch operatively connected to the operator displaceable lever for energizing the feeler positioning solenoid, a feeler relay for controlling the feeler positioning solenoid, contacts actuated by the feeler relay for short circuiting the operator displaceable switch and a time delay relay for opening the circuit to the feeler relay after a lapse of a predetermined time interval.

4. An inseam sewing machine for attaching a welt to a last supported Goodyear welt shoe upper and a sole member, said machine having stitch-forming, feeding and guiding devices for the shoe parts, a welt-severing knife mounted for movement toward and from the welt as it passes through the guiding devices, mechanisms for actuating the knife including an actuating solenoid and an armature connected to the knife, a feeler for engaging the leading end of the welt already attached to the shoe as that end approaches the stitch-forming devices a second time, a shiftable carriage on which the feeler is mounted for movement toward and from an operating position with relation to the shoe, yielding means for restraining the carriage in a position in which the feeler is held away from operating position with relation to the shoe, an operator displaceable lever and a pad on said lever disposed at a position convenient for engagement by the leg of the operator, in combination with a feeler positioning solenoid connected to the shiftable carriage, a switch operatively connected to the operator displaceable lever for energizing the feeler positioning solenoid, a feeler relay for controlling the feeler positioning solenoid, contacts actuated by the feeler relay for short circuiting the operator displaceable switch, a knife-actuating relay for energizing the welt-severing solenoid and a time delay relay for opening the circuit to the feeler relay and the knife actuating relay after a lapse of a predetermined time interval.

5. An inseam sewing machine for attaching a welt to a last-supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife to sever the welt, including a solenoid, an armature connected to the knife, and a feeler for engaging the leading end of the welt already attached to the shoe as that end approaches the stitch-forming devices, an alternating current supply line, a feeler-actuated switch and a knife-actuating relay having a set of contacts for connecting the welt severing solenoid to the alternating current supply line, and a coil connected to the feeler-actuated switch, in combination with a rectifier, and a condenser connected for charging by the rectifier and for discharging by the feeler-actuated switch through the coil of the knife actuating relay.

6. An inseam sewing machine for attaching a welt to a last-supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife to sever the welt, including a solenoid, an armature connected to the knife, and a feeler for engaging the leading end of the welt already attached to the shoe as that end approaches the stitch-forming devices, an alternating current supply line, a feeler-actuated switch and a knife actuating relay having a set of contacts for connecting the welt severing solenoid to the alternating current supply line, and a coil connected to the feeler-actuated switch, in combination with a rectifier, a condenser connected for charging by the rectifier and for discharging by the feeler-actuated switch through the coil of the knife-

actuating relay, a second set of contacts in the knife-actuating relay for continuing the supply of current to the relay coil after the feeler switch is opened, and a time delay device for opening the circuit through the welt-severing solenoid after the knife connected armature has completed its welt-severing stroke.

7. An inseam sewing machine for attaching a welt to a last supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife to sever the welt, including a solenoid, an armature connected to the knife, and a feeler for engaging the leading end of the welt already attached to the shoe as that end approaches the stitch-forming devices, an alternating current supply line, a feeler-actuated switch and a knife-actuating relay having a set of contacts for connecting the welt-severing solenoid to the alternating current supply line, and a coil connected to the feeler-actuated switch, in combination with a rectifier, a condenser connected for charging by the rectifier and for discharging by the feeler-actuated switch through the coil of the knife-actuating relay, a second set of contacts in the knife-actuating relay for continuing the supply of current to the relay coil after the feeler switch is opened, a knife-releasing relay having a normally closed set of contacts connected in series with the solenoid and a coil connected to one end of the welt-severing solenoid, a time delay relay having a coil also connected to one end of the welt severing solenoid and to said first set of contacts, and a set of contacts connected to complete the circuit between the said first set of contacts and the coil of the knife-actuating relay to cause the normally closed contacts of the knife relay to be opened after the knife connected armature has completed its welt-severing stroke.

8. A machine for manufacturing shoes with a welt attached to their marginal portions, said machine having a frame, stitch-forming, adjustable feeding and guiding devices for the shoe parts, a welt-severing knife mounted in the frame for movement toward and from the welt as it passes through the guiding devices, and mechanism for actuating the knife including a welt-severing solenoid, an armature operatively connected to the knife and a spring connected between the knife and the machine frame to retract the knife into inoperative position, in combination with manually actuated means for moving the knife into a cutting position relatively to the guiding devices to enable adjustment of the guiding devices.

9. A machine for manufacturing shoes with a welt attached to their marginal portions, said machine having a frame, stitch-forming, feeding and guiding devices for the shoe parts, a welt-severing knife mounted in the frame for movement toward and from the welt as it passes through the guiding devices, and mechanism for actuating the knife including a welt severing solenoid, an armature operatively connected to the knife and a spring connected between the knife and the machine frame to retract the knife into inoperative position, in combination with manually actuated means for moving the knife into a cutting position relatively to the guiding devices to enable adjustment of the guiding devices, and means for locking the knife against retraction by the spring consisting of a spring pressed plunger mounted in the frame and engaging an opening in the armature of the welt severing solenoid.

10. A machine for attaching a welt to the marginal portions of other shoe parts, said machine having attaching, feeding and guiding devices for the shoe parts, a welt-severing knife mounted for movement toward and from the welt as it passes through the guiding devices, mechanism for actuating the knife including a welt-severing solenoid and an armature connected to the knife, an alternating current supply line and a knife actuating relay having a set of contacts for connecting the welt-severing

solenoid to the alternating current supply line and a coil, in combination with a condenser and a rectifier connected to the condenser for charging it from the supply line, and means for discharging the condenser through the coil of the knife-actuating relay to energize the solenoid.

11. A machine for attaching a welt to the marginal portions of other shoe parts, said machine having attaching, feeding and guiding devices for the shoe parts, a welt-severing knife mounted for movement toward and from the welt as it passes through the guiding devices, mechanism for actuating the knife including a welt-severing solenoid and an armature connected to the knife, an alternating current supply line and a knife actuating relay having a set of contacts for connecting the welt-severing solenoid to the alternating current supply line and a coil, in combination with a condenser and a rectifier connected to the condenser for charging it from the supply line, an operator controlled switch for discharging the condenser through the coil of the knife-actuating relay, and a second set of contacts in the knife actuating relay for continuing the circuit through the relay coil after the condenser has been discharged.

12. A machine for attaching a welt to the marginal portions of other shoe parts, said machine having attaching, feeding and guiding devices for the shoe parts, a welt-severing knife mounted for movement toward and from the welt as it passes through the guiding devices, mechanism for actuating the knife including a welt-severing solenoid and an armature connected to the knife, an alternating current supply line and a knife actuating relay having a set of contacts for connecting the welt-severing solenoid to the alternating current supply line and a coil, in combination with a condenser and a rectifier connected to the condenser for charging it from the supply line, an operator-controlled switch for discharging the condenser through the coil of the knife actuating relay, a second set of contacts in the knife actuating relay for continuing the circuit through the relay coil after the condenser has been discharged, and a time delay relay for opening the circuit through the second set of contacts and the coil of the knife-actuating relay to insure a full cutting stroke of the knife connected armature.

13. A machine for attaching a welt to the marginal portions of other shoe parts, said machine having attaching, feeding and guiding devices for the shoe parts, a welt-severing knife mounted for movement toward and from the welt as it passes through the guiding devices, mechanism for actuating the knife including a solenoid and an armature operatively connected to the knife, a feeler for engaging the leading end of the welt already attached to the shoe parts as that end of the welt approaches the attaching devices, an alternating current supply line, and a knife actuating relay having a coil and a set of contacts for connecting the solenoid to the alternating current supply line, in combination with a condenser, a rectifier connected to the condenser for charging it, a safety relay under control of the operator having a coil, a feeler actuated switch for discharging the condenser through the coil of the knife-actuating relay to energize the solenoid, a set of contacts in the safety relay for preparing the circuit through the knife-actuating relay for closure, and switch means displaceable by the operator of the machine for completing the closure of the circuit through the coil of the knife actuating relay.

14. An inseam sewing machine for attaching a welt to a last supported Goodyear welt shoe upper and a sole member, said machine having a frame, stitch-forming, feeding and guiding devices capable of operating entirely around a shoe, a welt-severing knife mounted for movement toward and from the welt along a path inclined to the welt at a point in advance of the stitch-forming devices, mechanism for actuating the knife comprising a feeler for engaging the end of the welt first attached to the shoe as that end is approaching the sewing point a

second time, a shiftable carriage on which the feeler is mounted for bodily movement toward and from the sewing point, in combination with guideway means by which the movement of the carriage is confined to a path inclined toward the bulging shoe upper, a guard on the carriage extending along the welt-engaging end of the feeler and having a terminal extending into a position of engagement with the bulging upper of the shoe in line with the end of the welt first attached to the shoe, mechanism for actuating the carriage to move the feeler and guard toward the shoe being operated upon comprising a solenoid and an armature connected to the carriage, a spring acting between the carriage and the machine frame for moving the feeler and guard away from the shoe, and electrical circuits including a power supply line, a knife-actuating relay for connecting the welt severing solenoid to the supply line, a feeler-actuated switch for connecting the knife-actuating relay with the supply line, and a knife-releasing relay acting after the knife has completed its welt-severing stroke to disconnect the welt-severing solenoid from the supply line and to open the circuit to the knife-actuating relay.

15. A machine for attaching a welt to a last-supported Goodyear welt shoe upper and a sole member, said machine having attaching, feeding and guiding devices, an operating tool for performing an auxiliary operation on the shoe other than attaching, feeding or guiding the shoe parts during operation of said devices, mechanism for actuating the tool comprising a feeler for engaging the end of the welt first attached to the shoe as the welt is approaching the point of operation of the attaching devices a second time, a solenoid for actuating the tool, an electrical supply line, a feeler actuated switch for connecting the supply line with the tool actuating solenoid, a safety switch, a relay actuated by the safety switch to connect the feeler-actuated switch with the supply line and means displaceable by the operator for actuating the safety switch before the end of the welt first attached to the shoe approaches the point of operation of the attaching devices, and a time delay relay acting after the tool has completed its stroke to open the circuit of the tool actuating solenoid.

16. A machine for manufacturing shoes with a welt attached throughout their marginal portions including their heel seats or, alternatively, with a welt-attached about their foreparts only, said machine having stitch-forming, feeding and guiding devices for the shoe parts, a welt-severing knife mounted for movement toward and from the welt as it passes through the guiding devices, mechanism for actuating the knife including a solenoid and an armature connected to the knife, a feeler for engaging the leading end of the welt already attached to a sewed heel seat shoe, as that end approaches the stitch-forming devices, an electrical supply line, a knife actuating relay having a coil and a set of contacts for connecting the welt-severing solenoid to the supply line, and driving and stopping mechanisms for the machine including a treadle, in combination with a condenser, a rectifier connected to the condenser for charging it, a safety relay having a coil, a feeler actuated switch for discharging the condenser through the coil of the knife actuating relay to connect the welt-severing solenoid with the supply line, a set of contacts in the safety relay for preparing the circuit through the feeler actuated switch for closure, means controlled by the operator of the machine for completing the circuit through the coil of the safety relay, a second operator-controlled switch connected to the treadle for completing the circuit through the knife-actuating relay, and a selector switch having contacts in circuit with both operator controlled switches for enabling the welt to be severed either automatically by the engagement of the feeler with the leading end of the welt or by movement of the treadle.

17. A machine for manufacturing shoes with a welt attached throughout their marginal portions including

their heel seats or, alternatively, with a welt attached about their foreparts only, said machine having stitch-forming, feeding and guiding devices for the shoe parts, a welt-severing knife mounted for movement toward and from the welt as it passes through the guiding devices, mechanism for actuating the knife including a solenoid and an armature connected to the knife, a feeler for engaging the leading end of the welt already attached to a sewed heel seat shoe as that end approaches the stitch-forming devices, an electrical supply line, driving and stopping mechanisms for the machine including a treadle and a shiftable carriage on which the feeler is mounted for bodily movement toward and from the point of operation of the stitch-forming devices, in combination with a feeler positioning solenoid connected to the shiftable carriage for moving the feeler toward operating position, and means controlled by the operator of the machine for connecting the supply line with the feeler positioning solenoid.

18. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife including a solenoid and an armature connected to the knife, a feeler for engaging the leading end of the welt already attached to a sewed heel seat shoe as that end approaches the stitch-forming devices, an electrical supply line driving and stopping mechanisms for the machine including a treadle and a shiftable carriage on which the feeler is mounted for bodily movement toward and from the point of operation of the stitch-forming devices, in combination with a feeler positioning solenoid connected to the shiftable carriage for moving the feeler toward operating position, means controlled by the operator of the machine for connecting the supply line with the feeler positioning solenoid, and a selector switch having contacts in circuit with the feeler positioning solenoid to prevent movement of the feeler toward operating position while attaching a welt about the forepart only of a shoe.

19. An inseam sewing machine for attaching a welt to a last supported Goodyear shoe upper and a sole member, said machine having stitch-forming, feeding and guiding devices for the shoe parts, a welt-severing knife mounted for movement toward and from the welt as it passes through the guiding devices, mechanism for actuating the knife to sever the welt including a solenoid, an armature connected to the knife and a feeler for engaging the leading end of the welt already attached to the shoe as that end approaches the stitch-forming devices, a supply line, a feeler actuated energizing switch, a knife actuating relay having a set of contacts for connecting the welt-severing solenoid to the supply line and a coil connected to the feeler-actuated switch, and stopping mechanisms for bringing the machine to rest at the end of a seam, in combination with a secondary line switch actuated by the stop mechanism to disconnect the supply line from the solenoid and the feeler-actuated switch.

20. An inseam sewing machine for attaching a welt to a last supported Goodyear welt shoe upper and a sole member, said machine having stitch-forming, feeding and guiding devices for the shoe parts, a welt-severing knife mounted for movement toward and from the welt as it passes through the guiding devices, mechanism for actuating the knife including a solenoid and an armature connected to the knife, a feeler for engaging the leading end of the welt already attached to the shoe as that end approaches the stitch-forming devices a second time, driving and stopping mechanisms for bringing the machine to rest at the end of a seam in a predetermined position, a current supply line, a feeler-actuated switch

for connecting the supply line with a welt-severing solenoid, and a shiftable carriage on which the feeler is mounted for movement toward and from an operating position with relation to the shoe being operated upon, in combination with a line switch actuated by the stopping mechanism to disconnect the supply line from the knife-actuating solenoid, the feeler positioning solenoid and the solenoid energizing switch.

21. In a machine for sewing a welt to the marginal portions of a work piece, said machine having stitch-forming devices, driving and stopping mechanisms, a treadle for actuating the driving and stopping mechanisms to operate the stitch-forming devices and to bring them to rest, a guide for directing the welt toward the point of operation of the stitch-forming devices, a welt severing knife actuated against the welt in advance of the point of operation of the stitch-forming devices as the machine is being brought to rest at the end of a seam, and an auxiliary clutch also thrown into operation as the machine is being brought to rest, mechanism driven from the auxiliary clutch for gripping and advancing to a predetermined position beyond the point of operation of the stitch-forming devices, the end of the welt severed by the knife in preparation for attachment to a new work piece, said advancing mechanism comprising a continuously rotatable welt engaging wheel, and means for preventing operation of the knife and welt-advancing mechanism whenever a stitch is tightened with improper tension.

22. An inseam sewing machine for attaching a welt to a last supported Goodyear welt shoe upper and a sole member, said machine having a frame, stitch-forming and continuous work-feeding devices including a curved hook needle and a curved work piercing awl, separate feed slides for the needle and awl respectively, a cam shaft for operating the stitch-forming devices, cam actuated levers connected to the feed slides for imparting alternate work feeding movements of the needle and awl, and driving and stopping mechanisms for rotating the cam shaft and for bringing it to rest with the needle and awl disengaged from the work and with the needle about to enter the work during the next rotation of the cam shaft, in combination with means for advancing an end of welt before attachment to the shoe to a position between the points of engagement of the needle and awl during the first and second initial stitches in a new seam.

23. An inseam sewing machine for attaching a welt to a last supported Goodyear welt shoe upper and a sole member, said machine having a frame, stitch-forming and continuous work-feeding devices including a curved hook needle and a curved work piercing awl, separate feed slides for the needle and awl respectively, a cam shaft for operating the stitch-forming devices, cam actuated levers connected to the feed slides for imparting alternate work feeding movements of the needle and awl, and driving and stopping mechanisms for rotating the cam shaft and for bringing it to rest with the needle and awl disengaged from the work and with the needle about to enter the work during the next rotation of the cam shaft, in combination with means for advancing an end of welt before attachment to the shoe to a position between the points of engagement of the needle and awl during the first and second initial stitches in a new seam, and a welt-severing knife acting as the machine is brought to rest to form a bevel cut end on the welt with an obtuse angle ridge, the first and second stitches of a new seam extending across the ridge to hold the welt ends securely in place during completion of the seam.

24. An inseam sewing machine for attaching a welt to a last supported Goodyear welt shoe upper and a sole member, said machine having a frame, stitch-forming and continuous work-feeding devices including a curved hook needle and a curved work piercing awl, separate

feed slides for the needle and awl respectively, a cam shaft for operating the stitch-forming devices, cam actuated levers connected to the feed slides for imparting alternate work feeding movements of the needle and awl, and driving and stopping mechanisms for rotating the cam shaft and for bringing it to rest with the needle and awl disengaged from the work and with the needle about to enter the work during the next rotation of the cam shaft, in combination with means for advancing an end of welt before attachment to the shoe to a position between the points of engagement of the needle and awl during the first and second initial stitches in a new seam, a welt severing knife acting as the machine is brought to rest to form a bevel cut end on the welt with an obtuse angle ridge, the first and second stitches of a new seam extending across the ridge to hold the welt ends securely in place during completion of the seam, mechanism for actuating the knife comprising a feeler for engaging the obtuse angle ridge on the end of the welt first attached to the shoe as the welt is approaching the point of operation of the stitch-forming devices a second time, and connections between the feeler and the knife for severing the welt before the completion of the seam and at a position in which the angle of severance supplements the obtuse angle on the welt at its leading end with close fitting bevel surfaces.

25. In an inseam sewing machine for attaching a welt to a last supported Goodyear welt shoe upper and a sole member, said machine having a frame, stitch-forming and work-feeding devices in the frame and a welt-severing knife acting against the welt in advance of the point of operation of the stitch-forming devices as the machine is brought to rest, means for advancing the end of the welt remaining in the machine across the point of operation of the stitch-forming devices in preparation for the formation of a new seam, comprising a rotatable feed wheel having bevel peripheral welt-engaging surfaces forming an angle with its axis of rotation of approximately 40°.

26. In an inseam sewing machine for attaching a welt to a last supported Goodyear welt shoe upper and a sole member, said machine having a frame, stitch-forming and work-feeding devices in the frame and a welt-severing knife acting against the welt in advance of the point of operation of the stitch-forming devices as the machine is brought to rest, means for advancing the end of the welt remaining in the machine across the point of operation of the stitch-forming devices in preparation for the formation of a new seam, comprising a rotatable feed wheel having bevel peripheral welt-engaging surfaces forming an angle with its axis of rotation of approximately 40°, and a conical pressure roll, the conical angle of which is the same as that of the feed wheel to grip the welt against the feed wheel with a uniform force throughout the width of the welt.

27. In an inseam sewing machine for attaching a welt to a last supported Goodyear welt shoe upper and a sole member, said machine having a frame, stitch-forming and work-feeding devices in the frame and welt-severing knife acting against the welt in advance of the point of operation of the stitch-forming devices as the machine is brought to rest, means for advancing the end of the welt remaining in the machine across the point of operation of the stitch-forming devices in preparation for the formation of a new seam, comprising a rotatable feed wheel having bevel peripheral welt-engaging surfaces forming an angle with its axis of rotation of approximately 40°, and a double frusto-conical roll, one portion of which forms an angle with its axis of rotation of approximately 40° and the other portion of which is joined to the first portion with their smaller ends together to form a re-entrant right angle for the corner of the welt, the 40° angle portion acting to grip the welt against the feed wheel and the other portion serving as an edge gage for the welt.

28. In an inseam sewing machine for attaching a welt

to a last supported Goodyear welt shoe upper and a sole member, said machine having a frame, stitch-forming and work-feeding devices in the frame and a welt-severing knife acting against the welt in advance of the point of operation of the stitch-forming devices as the machine is brought to rest, means for advancing the end of the welt remaining in the machine across the point of operation of the stitch-forming devices in preparation for the formation of a new seam, comprising a rotatable feed wheel having bevel peripheral welt-engaging surfaces forming an angle with its axis of rotation of approximately 40°, and a bevel on the outer corner of the 40° portion to provide clearance for a bead on a storm welt.

29. A machine for sewing a welt to the marginal portions of a work piece, said machine having stitch-forming devices, driving and stopping mechanisms, a treadle for actuating the driving and stopping mechanisms to operate the stitch-forming devices and to bring them to rest, a guide for directing the welt toward the point of operation of the stitch-forming devices, a welt-severing knife actuated against the welt in advance of the point of operation of the stitch-forming devices as the machine is being brought to rest at the end of a seam, and an auxiliary clutch also thrown into operation as the machine is being brought to rest, in combination with mechanism driven from the auxiliary clutch for gripping and advancing to a predetermined position beyond the point of operation of the stitch-forming devices, the end of the welt severed by the knife in preparation for attachment to a new work piece, said welt end advancing mechanism including a three-armed lever, one arm of which is actuated by the auxiliary clutch, a one-way clutch for rotating the feed wheel connected to another arm of the lever and a pressure roll yieldingly mounted to grip the welt against the feed wheel and operatively connected to the third arm of the lever to cause the pressure roll to be retracted from the feed wheel after advancing the welt.

30. A machine for sewing a welt to the marginal portions of a work piece, said machine having stitch-forming devices, driving and stopping mechanisms, a treadle for actuating the driving and stopping mechanisms to operate the stitch-forming devices and to bring them to rest, a guide for directing the welt toward the point of operation of the stitch-forming devices, a welt-severing knife actuated against the welt in advance of the point of operation of the stitch-forming devices as the machine is being brought to rest at the end of a seam, and an auxiliary clutch also thrown into operation as the machine is being brought to rest, in combination with mechanism driven from the auxiliary clutch for gripping and advancing to a predetermined position beyond the point of operation of the stitch-forming devices, the end of the welt severed by the knife in preparation for attachment to a new work piece, said mechanism comprising a feed wheel and a pressure roll between which is gripped the end of the welt severed by the knife, said wheel and roll being mounted for relative yielding movement toward and from each other, connections between the auxiliary clutch and the feed wheel for rotating the feed wheel and for moving the pressure roll toward and away from the feed wheel to release the welt, a preliminary guide roll for directing the welt toward the feed wheel, and an antiretraction dog co-operating with the preliminary roll to prevent movement of the welt past the feed wheel when the pressure roll is moved away from the feed wheel.

31. A machine for sewing a welt to the marginal portions of a work piece, said machine having stitch-forming devices, driving and stopping mechanisms, a treadle for actuating the driving and stopping mechanisms to operate the stitch-forming devices and to bring them to rest, a guide for directing the welt toward the point of operation of the stitch-forming devices, a welt-severing knife actuated against the welt in advance of the point of operation of the stitch-forming devices as the machine

is being brought to rest at the end of a seam, and an auxiliary clutch also thrown into operation as the machine is being brought to rest, in combination with mechanism driven from the auxiliary clutch for gripping and advancing to a predetermined position beyond the point of operation of the stitch-forming devices, the end of the welt severed by the knife in preparation for attachment to a new work piece, said mechanism comprising a feed wheel and a pressure roll between which is gripped the end of the welt severed by the knife, said wheel and roll being mounted for relative yielding movement toward and from each other, connections between the auxiliary clutch and the feed wheel for rotating the feed wheel and for moving the pressure roll toward and away from the feed wheel to release the welt, a preliminary guide roll for directing the welt toward the feed wheel, an antiretraction dog co-operating with the preliminary roll to prevent movement of the welt past the feed wheel when the pressure roll is moved away from the feed wheel, and a slotted plate through which the welt passes before reaching the preliminary guide roll to remove kinks from the welt.

32. An inseam sewing machine for attaching a welt to a last supported Goodyear welt shoe upper and a sole member, said machine having a frame, stitch-forming devices including a curved hook needle and a curved work piercing awl, separate feed slides for the needle and awl respectively, a cam shaft for operating the stitch-forming devices to impart alternate work feeding movements to the needle and awl, and driving and stopping mechanisms for rotating the cam shaft and for bringing it to rest with the needle and awl disengaged from the work in laterally spaced relation in the direction of work feed and with the needle about to enter the work during the next rotation of the cam shaft, in combination with means for advancing an end of the welt before attachment to a shoe into a position between the needle and awl during the first and second initial stitches of a new seam to cause the needle to penetrate the shoe upper and sole member to the exclusion of the welt during the formation of the first stitch and the awl to penetrate the welt, upper and sole member during the formation of the second stitch in a seam.

33. A sewing machine for attaching a welt to a work piece, said machine having stitch-forming devices including a hook needle and a work piercing awl, driving and stopping mechanisms for causing the stitch-forming devices to be actuated and to be brought to rest at the end of a seam with the needle in spaced relation in the direction of feed from the awl, a guide for directing the welt toward the point of operation of the stitch-forming devices, and a welt-severing knife actuated against the welt in advance of the point of operation of the stitch-forming devices as the machine is being brought to rest at the end of a seam, in combination with mechanism for advancing the end of the welt severed by the knife to a position between the needle and awl in preparation for attachment to a new work piece.

34. A sewing machine for attaching a welt to a work piece, said machine having stitch-forming devices including a hook needle and a work piercing awl, driving and stopping mechanisms for causing the stitch-forming devices to be actuated and to be brought to rest at the end of a seam with the needle in spaced relation in the direction of feed from the awl, a guide for directing the welt toward the point of operation of the stitch-forming devices, and a welt severing knife actuated against the welt in advance of the point of operation of the stitch-forming devices as the machine is being brought to rest at the end of a seam, in combination with mechanism for advancing the end of the welt severed by the knife to a position between the needle and awl in preparation for attachment to a new work piece, the driving and stopping mechanisms being adjusted to cause the needle to enter the work to the exclusion of the welt as the

machine is started on a new seam, and the awl thereafter to penetrate the welt and the work piece during the formation of the second and succeeding stitches in the seam.

- 5 35. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket and operatively connected to the knife, in combination with a base 10 plate removably attached to the bracket, and a feeler mounted on the base plate for engaging the leading end of the welt already attached to a shoe as that end is approaching the point of operation of the attaching devices a second time to actuate the welt-severing knife.
- 10 36. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket, including a solenoid and an armature operatively connected to the 15 knife, in combination with a base plate removably attached to the bracket, a feeler mounted on the base plate for engaging the leading end of the welt already attached to a shoe as that end is approaching the point of operation of the attaching devices a second time to actuate the welt-severing knife and electrical circuits for energizing the knife-actuating solenoid whenever the feeler is engaged by the leading end of the welt, said circuits having flexible electrical cables running between the main frame of the machine and the knife-supporting bracket, on the one 20 hand, and between the knife-supporting bracket and the feeler base plate, on the other hand, to enable the knife-supporting bracket and the feeler base plate to be removed as a unit from the machine frame or, alternatively, the feeler supporting base plate to be removed from the knife-supporting bracket for individual servicing.
- 20 37. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket and operatively connected to the knife, in combination with a base 25 plate removably attached to the bracket, a feeler mounted on the base plate for engaging the leading end of the welt already attached to a shoe as that end is approaching the point of operation of the attaching devices a second time to actuate the welt-severing knife, a support on the knife-mounting bracket, and mechanism carried by the support for advancing toward the point of operation of the stitch-forming devices the end of the welt remaining in the machine after being severed by the knife.
- 25 38. In a machine for manufacturing a shoe with a welt attached to its marginal portion including its heel seat, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through the guiding devices and mechanism for actuating the knife also mounted on the bracket and operatively connected to the knife, a support removably attached to the bracket, and mechanism on the sup- 30 75

port for advancing toward the point of operation of the stitch-forming devices the end of the welt remaining in the machine after being severed by the knife to enable the knife-supporting bracket and the welt-advancing mechanism support to be removed as a unit from the machine frame or, alternatively, the welt-advancing mechanism support to be removed from the knife-supporting bracket for individual servicing.

39. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket and operatively connected to the knife, in combination with a guide on the bracket with its guiding surfaces extending in the direction of feed of the shoe, a slide in the guide, a base plate removably attached to the slide, and a feeler mounted on the base plate for engaging the leading end of the welt already attached to the shoe as that end is approaching the point of operation of the stitch-forming devices a second time to actuate the welt-severing knife.

40. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket and operatively connected to the knife, in combination with a guide on the bracket with its guiding surfaces extending in the direction of feed of the shoe, a slide in the guide, a base plate removably attached to the slide, a feeler mounted on the base plate for engaging the leading end of the welt already attached to the shoe as that end is approaching the point of operation of the stitch-forming devices a second time to actuate the welt-severing knife, and eccentric means for shifting the position of the slide in the guideway to bring the feeler to the proper point in the direction of feed, whereby a close fitting joint is obtained between the leading end of the welt and the final end of the welt formed by the operation of the severing knife.

41. An inseam sewing machine for manufacturing a shoe with a welt attached to its marginal portion, said machine having a main frame, stitch-forming, feeding and guiding devices for the shoe parts in the main frame, a welt-severing knife, a bracket detachably connected to the main frame, on which bracket the welt-severing knife is mounted for movement toward and from the welt as it passes through its guiding device, and mechanism for actuating the knife also mounted on the bracket and operatively connected to the knife, in combination with a guide on the bracket with its guiding surfaces extending in the direction of feed of the shoe, a slide in the guide, a base plate removably attached to the slide, a feeler mounted on the base plate for engaging the leading end of the welt already attached to the shoe as that end is approaching the point of operation of the stitch-forming devices a second time to actuate the welt-severing knife, and means for attaching the base plate to the slide with provision for vertical adjustment toward and from the bulging last-supported surface of the upper on the shoe while preventing movement of the base plate on the slide in a direction parallel to that of work feed.

42. A machine for manufacturing a shoe with a welt attached to its marginal portion, said machine having a main frame, stitch-forming, feeding and guiding devices for the shoe parts in the main frame, a welt-severing knife, a bracket connected to the main frame, on which bracket the welt-severing knife is mounted for movement toward

and from the welt as it passes through the guiding device, and mechanism for actuating the knife also mounted on the bracket including a solenoid and an armature operatively connected to the knife, in combination with an enclosing housing for the knife and the solenoid comprising two U-shaped interfitting plate members, one of which covers the upper, lower and rearward sides of the solenoid with an opening in the lower side for the knife and the other of which covers the right, left, and forward sides of the solenoid.

43. A machine for manufacturing a shoe with a welt attached to its marginal portion, said machine having a main frame, stitch-forming, feeding and guiding devices for the shoe parts in the main frame, a welt-severing knife, a bracket connected to the main frame, on which bracket the welt-severing knife is mounted for movement toward and from the welt as it passes through the guiding device, and mechanism for actuating the knife also mounted on the bracket including a solenoid and an armature operatively connected to the knife, in combination with an enclosing housing for the knife and the solenoid comprising two U-shaped interfitting plate members, one of which covers the upper, lower and rearward sides of the solenoid with an opening in the lower side for the knife and the other of which covers the right, left, and forward sides of the solenoid, and means for releasably securing together the plate members of the housing together comprising an open slotted tongue on the front covering plate member overlapping the upper portion of the rearward side covering member, a screw passing through the slot in the tongue and into the rearward side covering member and a screw at the lower end of the forward side covering member entering the solenoid mounting bracket.

44. An inseam sewing machine for attaching a welt to a last supported Goodyear welt shoe upper and a sole member, said machine having a frame, stitch-forming and continuous work-feeding devices including a curved hook needle and a curved work piercing awl mounted in the frame, separate feed slides for the needle and awl, respectively, a cam shaft for operating the stitch-forming devices, levers actuated by cams on the cam shaft, connected to the feed slides and formed with multiple fulcrum bearings for producing alternate feeding movements of the needle and awl, and means for advancing to a predetermined position with relation to the point of operation of the stitch-forming devices an end of welt before attachment to the shoe, in combination with means for adjusting the feeding movements of the needle and awl comprising selectively removable pivot pins for both the needle and awl feed levers, the spaced relationship of the bearings in the levers being such that the needle always will enter the hole pierced by the awl in the work regardless of the positions of the pins in the levers.

45. An inseam sewing machine for attaching a welt to a last supported Goodyear welt shoe upper and a sole member, said machine having a frame, stitch-forming and continuous work-feeding devices including a curved hook needle and a curved work piercing awl mounted in the frame, separate feed slides for the needle and awl, respectively, a cam shaft for operating the stitch-forming devices, feed slide connected levers actuated by the cam shaft and formed with multiple fulcrum bearings in each lever for producing adjustable alternate feeding movements of the needle and awl, and means for advancing to a predetermined position with relation to the point of operation of the stitch-forming devices an end of the welt before its attachment to the shoe, in combination with means for adjusting the feeding movements of the needle and awl comprising two selectively removable pivot pins for the needle and awl feed levers, and a yoke provided with multiple bores for receiving each of the pins, the bearings in the levers and the bores in the yoke being so located that they are all in register at a time in each sewing cycle while the needle is entering a perforation formed in the work by the awl.

46. An inseam sewing machine for attaching a welt to a last supported Goodyear welt shoe upper and a sole member, said machine having a frame, stitch-forming, and continuous work-feeding devices including a curved hook needle and a curved work piercing awl mounted in the frame, separate feed slides for the needle and awl, respectively, a cam shaft for operating the stitch-forming devices, feed slide connected levers actuated by the cam shaft and formed with multiple fulcrum bearings in each lever for producing adjustable alternate feeding movements of the needle and awl, and means for advancing to a predetermined position with relation to the point of operation of the stitch-forming devices an end of the welt before its attachment to the shoe, in combination with means for adjusting the feeding movements of the needle and awl comprising two selectively removable pivot pins for the needle and awl feed levers, a yoke provided with multiple bores for receiving each of the pins, the bearings in the levers and the bores in the yoke being so located that they are all in register at a time in each sewing cycle while the needle is entering a perforation formed in the work by the awl, and means for introducing lubricant into the bearings of the levers comprising a supply tube and axial passageways running in the needle and awl fulcrum pins and ducts in the yoke between the bores for the needle and awl pins, said needle lever pins being constructed with radiating passageways for carrying lubricant into the bores and the lever bearings.

47. An inseam sewing machine for attaching a welt to a last supported Goodyear welt shoe upper and a sole member, said machine having a frame, stitch-forming and continuous work-feeding devices including a curved hook needle and a curved work piercing awl mounted in the frame, separate feed slides for the needle and awl respectively, a cam shaft for operating the stitch-forming devices, feed slide connected levers actuated by the cam shaft and formed with multiple fulcrum bearings in each lever for producing adjustable alternate feeding movements of the needle and awl, and means for advancing to a predetermined position with relation to the point of operation of the stitch-forming devices an end of the welt before its attachment to the shoe, in combination with means for adjusting the feeding movements of the needle and awl comprising two selectively removable pivot pins for the needle and awl feed levers, a yoke provided with multiple bores for receiving each of the pins, the bearings in the levers and the bores in the yoke being so located that they are all in register at a time in each sewing cycle while the needle is entering a perforation formed in the work by the awl, means for introducing lubricant into the bearings of the levers comprising a supply tube and axial passageways running in the needle and awl fulcrum pins and ducts in the yoke between the bores for the needle and awl pins, said needle lever pins being constructed with radiating passageways for carrying lubricant into the bores and the lever bearings, and a plug in one of the pins to prevent flow of lubricant between the bore for the awl lever pin and a bore of the yoke in which the needle lever pin is omitted.

48. A chain stitch sewing machine for inserting an inseam in the marginal portions of a shoe, said machine having stitch-forming devices including a curved hook needle arranged to enter the work and during withdrawal with a loop of thread to tighten a previously formed loop, a looper for laying the thread in the hook of the needle, a thread finger acting to form a bight of thread between the work and the looper before the thread is laid in the needle hook during the next sewing cycle, a take-up for retracting each loop of thread drawn through the work by the needle and for tightening each loop about the shank of the needle while the needle engages the work during the formation of a succeeding stitch, a thread tension device against which the take-up acts while each loop is being tightened about the needle, a thread end gripping device acting to hold the thread running from the looper in a

position ready for engagement with the thread finger and to release the thread under tension while each loop is being drawn through the work by the needle, and driving and stopping mechanisms for causing the stitch-forming devices to be operated and to be brought to rest at the end of a seam with the needle disengaged from the work, in combination with means connected for actuation at the end of a seam by the driving and stopping mechanisms for measuring an amount of thread from the tension device, and for giving up the measured thread at the beginning of a succeeding seam while the thread finger is drawing out its bight of thread between the gripping device and the looper, and before the looper lays the thread in the hook of the needle.

49. A chain stitch sewing machine for inserting an inseam in the marginal portions of a shoe, said machine having stitch-forming devices including a curved hook needle arranged to enter the work and during withdrawal with a loop of thread to tighten a previously formed loop, a looper for laying the thread in the hook of the needle, a thread finger acting to form a bight of thread between the work and the looper before the thread is laid in the needle hook during the next sewing cycle, a take-up for retracting each loop of thread drawn through the work by the needle and for tightening each loop about the shank of the needle while the needle engages the work during the formation of a succeeding stitch, a thread tension device against which the take-up acts while each loop is being tightened about the needle, a thread cutter mounted on the machine at a position readily engageable with the thread as a sewn shoe is being withdrawn from the point of operation of the stitch-forming devices, a frictional thread end gripping device acting to hold the end of the thread formed after being severed by the knife in a position ready for engagement with the thread finger and to release the thread under tension while each loop is being drawn through the work by the needle in the first stitch of a new seam, and driving and stopping mechanisms for causing the stitch-forming devices to be operated and to be brought to rest at the end of a seam with the needle disengaged from the work, in combination with thread-engaging means connected for actuation at the end of a seam by the driving and stopping mechanisms for measuring an amount of thread from the tensioning device and for giving up the measured thread at the beginning of a seam while the thread finger is drawing out its bight of thread between the gripping device and the looper but before the looper lays the thread in the hook of the needle, the amount of thread measured by the thread-engaging means being sufficient to prevent the thread end from being drawn from the gripping device through the work while being tightened about the shank of the needle but insufficient to leave an excessive length of the thread end extending from the work in the first stitch of a seam.

50. An inseam sewing machine for attaching a welt to a last supported Goodyear shoe upper and a sole member, said machine having stitch-forming, feeding and guiding devices for the shoe parts including means for applying a setting tension to each stitch after being formed, a welt-severing knife mounted for movement toward and from the welt as it passes through the guiding devices, mechanism for actuating the knife to sever the welt including a solenoid, an armature connected to the knife and a feeler for engaging the leading end of the welt already attached to the shoe as that end approaches the stitch-forming devices, a current supply line and a feeler actuated switch for energizing the solenoid when the feeler engages the leading end of the welt, in combination with mechanism for opening the feeler switch circuit whenever the stitch-setting means fails to tighten a stitch with a predetermined tension.

51. An inseam sewing machine for attaching a welt to a last supported Goodyear shoe upper and a sole member, said machine having stitch-forming, feeding and guiding devices for the shoe parts including means for

applying a setting tension to each stitch after being formed, a welt-severing knife mounted for movement toward and from the welt as it passes through the guiding devices, mechanism for actuating the knife to sever the welt including a solenoid, an armature connected to the knife and a feeler for engaging the leading end of the welt already attached to the shoe as that end approaches the stitch-forming devices, a current supply line and a feeler actuated switch for energizing the solenoid when the feeler engages the leading end of the welt, in combination with a yielding thread tension responsive member and a switch actuated by the member upon loss of thread tension to open the circuit of the feeler switch whenever the stitch setting means fails to tighten a stitch with a predetermined thread tension.

52. An inseam sewing machine for attaching a welt to a last supported Goodyear shoe upper and a sole member, said machine having stitch-forming, feeding and guiding devices for the shoe parts including means for applying a setting tension to each stitch after being formed, a welt-severing knife mounted for movement toward and from the welt as it passes through the guiding devices, mechanism for actuating the knife to sever the welt including a solenoid, an armature connected to the knife and a feeler for engaging the leading end of the welt already attached to the shoe as that end approaches the stitch-forming devices, a current supply line and a feeler actuated switch for energizing the solenoid when the feeler engages the leading end of the welt, in combination with a yielding thread tension responsive member, a switch actuated by the member upon loss of thread tension to open the circuit of the feeler switch whenever the stitch-setting means fails to tighten a stitch with a predetermined thread tension, and means for locking the movement of the yielding member at all times except while each stitch is being set by the stitch-setting means.

53. An inseam sewing machine for attaching a welt to

a last supported Goodyear welt shoe upper and a sole member, said machine having stitch-forming, feeding and guiding devices for the shoe parts including a stitch-setting take-up, a welt-severing knife, mounted for movement toward and from the welt as it passes through the guiding devices, mechanism for actuating the knife to sever the welt including a solenoid, an armature connected to the knife and a feeler for engaging the leading end of the welt already attached to the shoe as that end approaches the stitch-forming devices, a current supply line, and a feeler actuated switch for connecting the current supply line to the solenoid, in combination with means for disconnecting the circuit through the feeler actuated switch to prevent operation of the welt severing knife upon loss of thread tension while the take-up is being actuated to set a stitch, comprising a yielding thread tension responsive member, a switch actuated by the tension responsive member and connected in circuit with the feeler actuated switch, and a latch controlled by the take-up for locking the yielding thread responsive member at all times except while the take-up is setting the stitch.
